UNITED STATES PATENT OFFICE.

JOHN PETER WEIS, OF NYACK, NEW YORK, ASSIGNOR, BY MESNE ASSIGNMENTS, OF ONE-HALF TO METROPOLITAN SEWING MACHINE CORPORATION, OF NYACK, NEW YORK, A CORPORATION OF DELAWARE.

SEWING-MACHINE AND CUTTING MECHANISM THEREFOR.

1,848,526.

Specification of Letters Patent.

Patented Aug. 3, 1920.

Application filed October 16, 1914, Serial No. 887,005. Renewed December 24, 1919. Serial No. 347,189.

To all whom it may concern:

Be it known that I, JOHN PETER WEIS, a citizen of the United States, residing at Nyack, in the county of Rockland and State of New York, have invented certain new and useful Improvements in Sewing-Machines and Cutting Mechanisms Therefor, of which the following is a specification.

This invention relates to sewing machines and cutting mechanism therefor. Some features of the present invention relate particularly to the combined cutting-and-sewing machine described in my United States Patent No. 1,114,082, granted October 20, 1914, while other features of the invention are of more or less general applicability. However all the features in the present invention constitute improvements in the combined cutting-and-sewing machine mentioned, and the objects of the invention are generally so to improve the combined cutting-and-sewing machine that it will be more highly efficient and durable when operating at a very high speed. In actual practice the top shafts of the sewing machines contained in the combined cutting-and-sewing machine are operated at a speed of about 4000 revolutions per minute and are stopped instantly by the stop-motions described below, arresting the needles instantly at the completion of their up strokes. This great speed desirable for high productivity introduces many strains and stresses into many portions of the combined cutting-and-sewing machine in its entirety, and to insure durability and efficient relations of co-operating parts under the actual conditions due to the great speed at which the sewing-machine top-shafts are operated requires a minimum of all strains and stresses throughout the entire machine and a lubricating system of efficient capacity and action. Some of the new features of the present invention relate particularly to the manufacture of union suits, which are an important product of this combined cutting-and-sewing machine.

In the accompanying drawings forming a part hereof,

Figure 1 is an end view of the main start-

ing and stopping mechanism, and shows electrical connections therefor.

Fig. 2 is a plan view of a starting and stopping mechanism with its belt guard removed.

Fig. 3 is an elevational view of stop-latch mechanism forming a part of the main stopping and starting mechanism.

Fig. 3^a is a side elevation of the fly-belt wheel with clutch members carried thereby.

Fig. 4 is a top plan view of what is shown in Fig. 1, the electrical connections being omitted.

Fig. 4^a is a detail view showing a slide-bar which forms part of the main starting and stopping mechanism. The bar is partly in longitudinal section to show the spring-controlled latch carried by it.

Fig. 5 is a view partly in side elevation and partly in upright slanting section at line 5—5 of Fig. 7 of the left-hand sewing-machine, the front wall of which is broken away more clearly to show the working mechanism. Parts carried by the front wall of the sewing machine are shown in working position, these parts pertaining to the thread-controlling mechanism and the stop-motion for the top-shaft or needle-actuating shaft of the sewing machine. This view also shows in front elevation part of the actuating mechanism for the thread-controlling devices; and indicates parts of the lubricating system and goods-trimming and thread-breaking mechanisms. The view also shows certain connections carried by the sewing-machine frame for connecting it with a master cam not shown in this view.

Fig. 6 is a front elevation showing the master or pattern cam, connections between it and a sewing-machine frame, a lower band-cutter-wheel carried by the sewing-machine frame, and on the master cam certain auxiliary cams and portions of connections between the auxiliary cams and a goods-trimming mechanism and a thread-breaking mechanism, a thread-controlling mechanism and a stop-motion on the top shaft.

Fig. 6^a is a side elevation of the master or pattern cam provided with auxiliary cams.

for starting and stopping the stitch-forming instrumentalities and for actuating the goods trimming and thread breaking mechanisms, a crotch-piece cutting mechanism, and 5 a side-slitting mechanism.

Fig. 7 is an end view of what is shown in Figs. 5 and 6, but partly in section at line 7—7 of Fig. 8. This view also shows in end elevation a looper and needle for making a 10 two-thread chain stitch.

Fig. 7^a is an end elevational diagram of the auxiliary cam on the master cam, and roller therefor, whereby the goods-trimming mechanism is actuated.

Fig. 7^b is an end elevational diagram of a 15 pair of auxiliary cams on the master cam and of a pair of rolls, one of which coöperates with one of the cams for actuating a cutter for transversely severing a crotch-piece at its ends and the other of which 20 co-operates with the other of the cams for actuation of side-slitting mechanism.

Fig. 8 is an elevational view, certain parts 25 being removed for greater clearness, of the mechanical connection of one sewing machine in its relation to the other sewing machine with which the combined machine is provided, and the relations of both sewing machines to the master cam. The view also 30 shows in side elevation a motor carrying a side-slitting knife, and also the upper one of a pair of auxiliary feeding rolls located in front of the main feed rolls. The view also shows mechanical connections between 35 the master cam and the crotch-piece end-cutter mechanism, and shows a portion of another connection for the master cam for swinging the motor that carries the side-slitting knife from and toward its work.

Fig. 9 is a left-hand end elevational view 40 of one of the sewing machines in place on a track, the view also showing various other mechanisms including the mechanical connections between the main shaft of the organized cutting-and-sewing machine and a 45 gear-carrying shaft from which the pattern cam is rotated.

Fig. 10 is a partial front elevational view 50 of the starting rails, their actuating mechanism, and connections with the master cam. This view also shows two sets of throat or 55 needle-hole plates, one for one and the other for the other sewing machine, together with their thread-breaking devices, but these throat-plates and thread-breaking devices are shown in top plan view.

Fig. 11 is a perspective view of parts of a 60 thread-breaking trip-mechanism and of a thread-measuring mechanism.

Fig. 12 is a perspective view showing the 65 coupling yoke of the thread-measuring mechanism.

Fig. 13 is a diagrammatic view of the master cam and of an auxiliary cam thereon,

and of a roller coöperating therewith for starting and stopping a sewing machine. The view shows said auxiliary cam as having thin end-portions which coöperate with the roll for actuating the thread-breaking mechanism.

Fig. 14 is a top plan view, and

Fig. 15 is a side elevation, of a mechanism for connecting the thread-breaking and thread-controlling mechanisms.

Fig. 16 is an elevational detail of the 75 main feed-rollers and a pair of auxiliary feed-rollers in front of the main feed-rollers, the lower auxiliary feed-roller being partially broken away for greater clearness. The view also shows a cutting mechanism 80 for transversely severing the opposite ends of a crotch-piece removed from goods forming drawers or union suits. This view also shows portions of connections leading to the master cam, not shown in this view; and 85 also a sewing-machine track provided with electrical conductors and insulation.

Fig. 17 is a top plan view, and

Fig. 18 is a side view, of an electric switch mechanism for stopping the entire machine 90 on breakage of a thread in either or both sewing machines.

Fig. 19 is a top plan view of the actuating mechanism for the crotch-piece cut-off mechanism and of the driving means for the auxiliary feeders, the latter not shown in this view.

Fig. 20 is a perspective view of a bearing 95 for the crotch-piece cutting-off cutter's driving slide.

Fig. 21 is an elevational view of the crotch-piece cutting-off cutter and connected parts.

Fig. 22 is a right-hand end view of the 100 main feed-rolls and their gear connections. This view shows the lower auxiliary feed-roll connected with one of the gears.

Fig. 23 is a perspective showing the main feed-rolls, the upper and lower auxiliary feed-rolls in front of the main feed-rolls, 110 the crotch-piece cutting-off mechanism, and motors for driving the side-slitting cutters.

Fig. 24 is a perspective of a portion of the goods spreader and a side-slitting cutter in cutting position.

Fig. 25 is an end view of a side-slit cutting mechanism and its motor. The view is partially in vertical section at line 25—25 of Fig. 23.

Fig. 26 is a sectional elevation at line 120 26—26 of Fig. 27, and

Fig. 27 is an end view of a side-slitting cutter and a guard therefor.

Fig. 28 is a transverse sectional view at line 28—28 of Fig. 23, looking in the direction of the arrow shown in Fig. 23, and shows the main feed-rolls, the auxiliary feed-rolls, the crotch-piece cutting-off cutter,

and a crotch-piece deflector. In this view the auxiliary feed-rolls are out of engagement with the goods, the main feed-rolls are assumed to be feeding the goods, and the crotch-piece deflector and cutting-off cutter are out of engagement with the goods. An arrow shows the direction of the feed of the goods.

Fig. 29 is a view similar to Fig. 28, but shows the crotch-piece deflector and cutter in engagement with the goods, and the auxiliary feed-rolls also in engagement with the goods. The dotted lines in Fig. 29 indicate a severed end of the crotch piece.

Fig. 30 shows the same parts shown in Figs. 28 and 29, but here the dotted lines indicate the crotch piece being severed at the other end.

Fig. 31 shows in three positions the goods and the jig-knife and a therewith-coöperating cutter-blade for use in slitting one or more opposed walls of tubular goods to form front or back openings.

Fig. 32 is a lay-out of a pair of union suits and the beginning of a third, all made from a straight piece of tubular goods. The view shows a crotch-piece removed from two adjacent garments.

Fig. 33 shows the crotch-piece cut from two adjacent union suits as indicated in Fig. 32.

Fig. 34 is a diagram illustrating the cutting of the jig-knife at three different heights.

Fig. 35 is an end view of the jig-knife mechanism.

Fig. 36 is a perspective of the throat or needle plate and the jig-knife in coöperating relations.

Fig. 37 is a perspective view of the needle guard and holder for the cutter blade that coöperates with the jig-knife.

Fig. 38 is a view showing a driving wheel for the jig-knife.

Fig. 39 is a sectional view at line 39—39 of Fig. 38, looking in the direction of the arrow, and illustrates constructional features of the drive wheel and lubricating means.

Fig. 40 is a view, partly in side elevation and partly in vertical section at line 40—40 of Fig. 62, of a stop-motion, one of which is provided for each top shaft of the sewing machine.

Fig. 41 is an end view of a stop finger and oil buffer forming part of the stop motion.

Fig. 42 is a side view of what is shown in Fig. 41.

Figs. 43, 44 and 45 are details of the stop-motion buffer parts; Fig. 43 showing a thimble partially in section; Fig. 44 showing a bushing in side elevation; and Fig. 45 showing the bushing in end view looking in the direction of the arrow shown in Fig. 44.

Fig. 46 is a detail of the stop-motion 65 clutch-wheel, partly in section at line 46—46 of Fig. 47, looking in the direction of the arrow shown in Fig. 47.

Fig. 47 is an elevational view, partly in section at line 47—47 of Fig. 46, of the stop-motion clutch-wheel. This view shows the clutch-balls engaged so as to drive the top shaft of the sewing machine.

Fig. 48 is a view similar to Fig. 47, but shows the clutch-balls in non-tripping relation to the shaft.

Fig. 49 shows details of the sewing-machine top shaft in its relation to the stop-motion.

Fig. 50 is a side view, and

Fig. 51 is a transverse section at line 51—51 of Fig. 50, of a sleeve forming a part of the stop-motion.

Fig. 52 is an end view of the stop-motion clutch-wheel assembled with the sleeve 35 shown in Figs. 50 and 51 and with the top shaft and a spring.

Fig. 53 is a detail of a wedge block forming part of the stop-motion.

Fig. 54 shows in the side and end views 90 a brake-shoe forming part of the stop-motion.

Fig. 55 shows in side and end views the brake-shoe pressure-plug forming part of the stop-motion.

Fig. 56 is a perspective view of the stop-motion brake-shoe lever.

Fig. 57 is a sectional view of an end bearing for the top shaft, partly in section at line 57—57 of Fig. 46.

Fig. 58 is an elevational diagrammatic view of one of the sewing machines, and a band-cutting mechanism carried thereby, and shows a thread-controlling mechanism in full, and a sewing-machine frame in 105 dotted lines. This view also shows electrical mechanism for stopping the entire machine when a thread breaks.

Figs. 59 and 60 are perspective views illustrating the thread-controlling mechanism.

Fig. 61 is a top plan view of a trip-lever actuated when the thread breaks, and forming part of the thread-controlling mechanism.

Fig. 62 is a side elevation of a sewing-machine frame, a driving motor therefor, and shows particularly an oil reservoir and an oil pump carried by the frame and forming part of the lubricating system of a sewing machine comprised in the combined machine.

Fig. 63 is an enlarged front end view of what is shown in Fig. 62, and more plainly illustrates the needle-actuating mechanism and looper already referred to for forming 125 a double chain stitch.

Fig. 64 is a perspective view of the needle-driving crank.

Fig. 65 shows top and side views of the needle holder.

Fig. 66 is an end view of the needle holder partly in section at line 66—66 of Fig. 65, 5 with its driving link.

Fig. 67 is a perspective view of the needle-holder guide.

Fig. 68 is a top plan view of the throat or needle-hole plate, and shows the thread-breaker in two positions, the full-line position indicating its operative position, and 10 the dotted line position indicating its inoperative position.

Fig. 69 is a perspective view of the 15 thread-breaker plate.

Fig. 70 is an end elevation of what is shown in Fig. 68, looking in the direction of the arrow shown in Fig. 68.

Figs. 71 and 72 are partial sectional views 20 of the throat plate, thread breaker slide, and a plate carried by the throat plate. Both figures are sectioned at line 70—70 of Fig. 70, looking in the direction of the arrow shown in Fig. 70, and illustrate the 25 looper in different positions operating on the looper thread, and also show the manner in which the thread is clamped and broken. Fig. 71 shows the thread-breaker in its operative position during the formation of the stitching, and Fig. 72 shows the 30 thread-breaker in thread-breaking position after the stitching is completed.

Fig. 73 is an end view of the throat plate, presser foot, and looper, assembled.

Fig. 74 is a perspective view illustrating the manner in which two lines of double chain stitching are formed by providing a sewing machine with two stitching mechanisms.

Fig. 75 shows details of the needle-actuating link and the needle-thread nipper in open and closed positions.

Fig. 76 shows details of a two-thread over-stitch mechanism which may be used in 45 each sewing machine if desired. This view is looking in the direction of the arrow shown in Fig. 77.

Fig. 77 is a top plan view of what is shown in Fig. 76, and illustrates the making of the over-stitch on the goods.

Fig. 78 is an end elevation of the over-stitch mechanism and its actuating means.

Fig. 79 is a side elevation of what is shown in Fig. 78, the frame being sectioned 55 at line 79—79 of Fig. 78, looking in the direction of the arrow thereon.

Figs. 80, 81, 82 and 83 are diagrammatic views showing different steps in the formation of the over-stitching.

Fig. 84 is a lengthwise sectional view of the upper and under arms of a sewing machine. This view shows the top shaft, 60 looper shaft, connecting mechanisms between said shafts, stop-motion mechanism, 65 and various features of the lubricating sys-

tem, together with the needle-actuating and looper-actuating devices.

Fig. 85 is a vertical sectional view at line 85—85 of Fig. 86, and illustrates the oil reservoir and oil pump construction. 70

Fig. 86 is a side elevation of the oil reservoir, oil pump, driving pulley, and certain driving belts, a wall of the reservoir being broken away to show a wall of an interior oil-filtering chamber. 75

Fig. 87 illustrates the two gear members of the oil pump.

Fig. 88 is a view of the pump casing with its cover plate removed.

Fig. 89 is an inside view of the pump 80 cover plate.

Referring to the drawings:

In the present structure the main shaft 4 has a continuous speed as in my Patent No. 1,114,082 of October 20, 1914, and is provided (Fig. 9) with a beveled gear g in mesh with a beveled gear g' on the upper end of a vertical shaft g^2 which at its lower end has a worm g^3 that meshes with a worm wheel gear g^4 on a transverse shaft g^5 that corresponds to the shaft 297 (Fig. 4) of 90 said patent.

Driving and main-shaft clutch mechanism.—Power for the machine is preferably provided by an electric motor 1 driving a belt 2 which operates on the fly-wheel 3 that is loosely mounted on the main shaft 4 of the machine. This fly-wheel has a laterally-projecting annular rim 5, and therewith there coats in starting or stopping the 100 machine a pair of arc-shaped spring-plates 6 carried on spider arms 6^a from a hub 6^b which is pinned at 6^c to the main shaft, the spring-plates 6 being nested within the inner periphery of the annular rim 5 of the fly-wheel. The spring-plates are in effect a split ring, one member of which is carried by one spider arm 6^a and the other of which is carried by another spider arm 6^a . The 105 free ends of the spring-plates are provided with projecting portions 6^d each opposed to an end of a clutch-lever 6^e which is pivoted at 6^f to each outward end of a spider arm 6^a , so that there are two of the clutch-lever arms 6^e and these are pivoted diametrically 110 opposite one another. The inward ends of these levers are severally provided with projections 6^g which are also diametrically opposite each other. On the main shaft, adjacent the fly-wheel rim 5, there is loosely mounted a sliding clutch spool 7 having a beveled end which is adapted to be slid between the opposed projections 6^g and wedge them apart. Thereby the outward 115 ends of the clutch levers 6^e are simultaneously pressed each against an opposed projection 6^d of a spring-plate 6, expanding the same so that the peripheries clutchingly engage the inner wall of the fly-wheel rim 120

5. The clutch spool 7 has between its ends 125

130

an annular groove within which project diametrically opposite pins 7^a each of which is carried by an arm 8 fixed at 8^a on the starting post 9 of the machine, this post standing vertically at right-angles to and at one side of the main shaft 4. The starting post 9 is rockable in bearings 10 which are integral with the fly-wheel guard-casing 11 fixed to the main frame of the machine at one end thereof. A lever 12 is fixed at 12^a to the upper end of the starting post 9. The other end of this lever has a vertical joint connection at 12^b with one end of a link 13 which at 13^a has a horizontal link connection with another link 13^b which at 13^b has a vertical joint connection with a trolley rail 14 that extends horizontally in front of one of the sewing machines.

The periphery of the fly-wheel rim 5 is provided with a projecting cam 15 which in its rotation with the fly-wheel contacts at intervals with the lower end of a vertical slide 16 mounted to reciprocate vertically in a swinging bracket 17 which is provided with a recess 18 for the slide, which has a lengthwise-extending recess 19 in one of its sides to receive the latch 20 which is pivoted at 21 near an end of the recess 19. A spring 22 is mounted between the back wall 30 of the recess 19 and the opposed edge of the latch 20, the spring serving to project the free end of the latch outwardly of the slide. This slide 16 is provided with a notch 23 to contact with a tooth 24 carried by one arm of the bell-crank lever 25 which is pivoted at 26 to the swinging bracket 17. The other arm 27 of this bell-crank lever is extended to contact intermittently with the two poles A of a magnet B mounted on an extension 28 of the upper bearing 10. An electric switch C carries a signal lamp D having an electric connection E extending to the parallel conductor rails F mounted on the sewing machine track 381, the latter extending crosswise of the machine for support of two sewing machines, and the rails also extending crosswise of the machine as described below. The conductor rails F are adapted to engage with electrical contacts G forming a switch connection by means of the conductor H which extends from the upper contact G to a conductor I carried by the switch-lever J which is pivoted at 377 (Fig. 5) to a bracket 378 carried by the main frame.

The swinging bracket 17 is journaled on the starting post 9 between the upper and under bearings 10, and swings freely on the starting post. It is cut out at 29 on its post-encircling edge, and a rocker arm 30 is fixed to the starting post within this cut-out, the free end of the rocker arm overlapping one side of the swinging bracket so that when the starting post is rocked in one direction to start the machine the rocker arm 30 pushes the swinging bracket in a correspond-

ing direction. Guard casing 11 has secured to it one end of a bow 31, the other end of which is secured at 32 to the end-bearing 33 of the main shaft. Intermediate the ends of bow 31 one end of a coil spring 34 is attached to it, the other end of the spring being connected to the bracket 17 at 35. Consequently the pushing movement of the rocker arm 30 against the bracket for swinging the latter on starting of the machine is exerted against the tension of the coil spring 34. Bracket 17 is provided with an extension 36 which is adapted to engage a latch 37 which is pivoted to the casing 11 at 38. The free end of the latch 37 extends at 39 over the upper free end of the latch 20 and is provided on its under side with a catch-tooth 40 to engage the extension 36. Latch 20 carried by the vertical slide 16 engages the under side of the portion 39 of the latch 37 to lift the catch-tooth 40 out of engagement with the extension 36 when the slide 16 is forced upwardly by the cam 15. When the starting post 9 is rocked in order to start the machine, the spool 7 is slid along the main shaft so as to wedge apart the projection 6^a and thereby force the spring-plates 6 against the fly-wheel rim 5, whereby rotation of the fly-wheel imparts to the main shaft rotary movement through the spider hub 6^b fixed to the main shaft at 6^c. The sliding movement of the spool just referred to is accomplished through the rocking of the arms 8 fixed to the starting post. During this rocking movement of the starting post whereby the spool 7 is given its just-described movement, the rocker arm 30 rocks the swinging bracket 17 against the tension of the spring 34 into the dotted line position indicated in Fig. 4. In this movement the latch 20 is swung in the arc of a circle beneath the under edge of the latch 37, raising the latch sufficiently to permit its tooth 40 to drop over the upper edge of the extension 36 and then fall back of the extension 36 and thereby hold the extension 36 and the bracket 17 in the dotted line position of Fig. 4, against the tension of the spring 34. In this position of the parts the starting post may be rocked to start or to stop the machine, including both sewing machines, manually as often as desired. The purposes of locking the swinging bracket 17 in its position against the tension of the spring are: first, to hold the bell-crank arm 27 which serves as an armature, in a position opposed to the magnet poles A; and secondly, to swing the under end of the slide 16 into a position above and clear of the path of the cam 15 on the fly-wheel. This locked position of the slide 16 and armature 27 of the bell-crank 25 may be called the thread-breaking emergency position, and if a thread breaks, as elsewhere described, a current energizing the magnet poles A will 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 pull the armature 27 of the bell crank 25 toward the poles and thereby release the tooth 24 from the notch 23 (a position shown in Fig. 3) and allow the slide 16 to drop by gravity into the path of the cam 15, the weight of the slide being sufficient to effect the compression of the light spring 22 and permit the free end of the latch to ride past the end portion 39 of lever 37. As the cam 15 is rapidly rotating, on the breakage of a thread it will almost instantly strike the under side of the slide 16 and push the slide upwardly so that the then-projecting free end of the latch 20 will raise the lever 37 carrying the tooth 40 out of contact with the bracket extension 36 and permit the spring 34 to swing the bracket 17 into the full-line position shown in Fig. 4, whereupon the machine is instantly stopped. At this moment the armature end 27 of the bell crank is carried out from under the poles A, the bell crank rocks on its pivot and the tooth 24 drops into the notch 23 to reengage the slide 16. In Fig. 3 the dotted-line positions of the bell-crank-lever 25 and the slide 16 indicate the thread-breaking emergency position, while the full-lines represent the parts at the moment of the breaking of the thread. By the construction described, the machine is automatically stopped on the breaking of a thread without appreciable shock, the spring 34 having a power just sufficient to move the bracket 17 gently instead of violently, and thereby move the rocker arm 12 and starting post gently instead of violently, and thereby move the starting lever 12 and its connections with the trolley rail, and the trolley rail, all gently and not violently on the automatic stopping of the machine due to thread breakage.

When the starting post is rocked to obtain its clutched relation to the main shaft, the projection 36 rides against the back side of the tooth 40, thereby lifting the lever 37. A projection 36 moves under the tooth to the front side thereof, the free end of the lever 37 falling by gravity. In said rocking movement the tooth 40 is pushed into its locking position with projection 36 against the tension of the spring 34, and the armature 27 is carried under, but not into contact with, the magnet A. The slide 16 then has its under end raised above the path of the cam 15 and is held in its lifted position by engagement of its notch 23 with the tooth 24 on the under arm of the bell-crank armature. If either thread of either sewing machine breaks, the said parts in said position, the magnet is energized, the armature lifted, and the tooth 24 pulled out of its engagement with the notch 23 of the slide 16, which then drops so that its under end is in the path of the cam 15. When this cam pushes the slide up, the tooth 20 engages the free end of the lever 37 and lifts it for disen-

gagement of its tooth 40 with the projection 36, whereupon the spring 34 then pulls the bracket 17 outward against the fixed arm 30 on the starting-post, rocking the latter, moving the clutch-spool 7 outward out of clutching position in relation to the main shaft; whereupon the fly-belt-wheel runs idle and the machine is stopped.

The starting-post starting-lever link and trolley-rail system.—The trolley rail 14 above referred to, has a pair of vertical rail-actuating levers 41 pivoted to it at 42. An intermediate link 43 connects the trolley rail 14 for one sewing machine with an aligned and corresponding trolley rail 44 for the other sewing machine, the trolley rail 44 also having trolley-rail actuating vertical links 41 pivoted to it at 42. As there are two sets of these trolley rail mechanisms and their connections with the master cam, one set being used in connection with a right-hand, and the other in connection with a left-hand sewing machine, description of one set will suffice for description of both sets. The links 41 extend downward through a transverse horizontal table 45 with which the machine is provided, and are each pivoted at 46 to an end of a horizontal arm of a bell-crank lever 47 which is pivoted at 48 to the main frame. The lower and free ends of the vertical arms of each of these bell-crank levers 47 are connected by a horizontal link 49. The ends of the links 49 are each pivoted at 50 to an end of the vertical arm of each bell crank 47. From the pivot 50 of the outward bell crank 47 (Fig. 8) a link 51 extends inwardly toward the center of the machine to a pivot pin 52, the end of the link 51 engaging with the pivot pin 52 having an elongated slot 53. The pivot pin 52 projects from each side of the upper end of the vertical arm 55 of the bell-crank lever which is pivoted at 56 to a bracket 57 carried by a frame member 58. The other and horizontal arm 59 of the bell crank is provided with a roller 60 which cooperates not only with the pattern cam 61, but also with a projecting cam portion 62 of the pattern cam, and also with low end portions 63 of the projecting cam 62. The projecting cam surfaces 62 and 63, 63 are integral and aligned (Figs. 6^a and 13). The surface 62 represents that period during each complete rotation of the pattern cam during which the sewing machine under its influence is stitching and therefore may be called the stitching cam. As shown in Figs. 6^a and 10 the pattern cam carries two stitching cams, one for each sewing machine. Each cam 63 is both a thread-measuring and a thread-breaking cam, each serving to throw the thread-measuring devices into and out of operation, and also to throw the thread-breaking mechanisms into and out

of operation. The cam surfaces 63 are each of short length compared to the length of the cam surface 62 which is stepped up at 64 to a greater height than the cam surfaces 63. A stop-motion for the top shaft of each sewing machine is provided with a trolley wheel 65 that rides either on the trolley rail 14 or 44 as the case may be (Figs. 7 and 9). Each trolley wheel 65 is carried by a hanger 66, the lower end of which is pivoted at 67 to a stop-motion control-lever 68 of the stop-motion provided for the top shaft of each sewing machine.

In the present construction the trolley rails 14 and 44 and the links 13 and 43 are all lifted positively through the rollers 60, the bell cranks 47, the link 51, and the upright actuating links 41, and the cam 60 on the master cam. This positive raising of the trolley tracks is an important feature of the present machine because it insures the lifting of the trolley tracks to the proper height for proper actuation of the stop-motions for the sewing-machine top shafts.

When the machine is manually started or stopped by shifting the rails 14, 44, the links 41 swing on the pivots 42 and 46 so that to stop the machine the rails 14, 44 are moved in the direction of the arrow in Fig. 8, and the links 41 swing all to one side of the vertical position shown, thereby bringing the rails 14 and 44 to a lower position for actuating the stop control lever 68 and the post 9. To start the machine, the rails 14 and 44 are moved in the other direction to the position shown in Fig. 8.

The sewing machines and needle actuation.—Each of two sewing machines (Figs. 5, 8, 62 and 84) comprises an upper hollow arm 69, a lower hollow base 70, a rear end trunk or casing 71 affording space for working parts within the chamber of the trunk, a depending web 72 provided with wheels 73 that are journaled at 74 and travel on a track 75 extending transversely of the machine and supported by its frame. Each sewing machine has a depending web 76 opposed to and spaced apart from the web 72, and the lower band-knife wheel 77 is journaled in the space between these two webs (Fig. 7). A band knife 78 operates on each lower wheel 77 and thence extends around a top wheel 79 carried by a support 80 secured to the top of the sewing-machine frame at 81. A portion of a run of each band knife operates adjacent a needle or needles of each sewing machine. The upper arms 69 of each sewing machine contains a lengthwise-extending tube 82 in which a built-up top-shaft 83 is contained, being therein mounted in bearings 84. The diameter of each top shaft is reduced at 85, forming a shoulder 86, and a crank arm 87 is secured to the

front end of the shaft. Shoulder 86 bears against an adjacent bearing 84 to prevent the shaft from moving endwise. The crank arm is provided with a crank pin 88 for a needle-driving link 89. The needle-driving link is pivoted at 90 to the needle holder 91 which carries a needle 92. The needle holder has a hole 91a through it for reception of, and reciprocates on, a guide-bar 93, and is provided with tongues 94 one 75 above the other, that work in a groove 95 formed in a side wall of a needle-holder guide 96. A plate 97 forms one wall of said groove, and the needle-holder guide 96 has a hub 98 which is secured in the free end of the upper hollow arm 69 at 99. The top shaft comprises a section 83 and a section 100 for convenience of manufacture, these sections being endwise united. The tube carrying the top shaft and its bearings is centered in 85 the chamber of the top arm by the screws x.

Sewing-machine stop-motion.—Section 100 is formed with ball cranks 101 and 102 spaced apart one from the other. Rearwardly of these cranks, section 100 has an 90 enlarged portion 103 formed circumferentially with three pockets 104 at 120° apart, to receive the segmental wedges 105, one flat edge of which, from the curved to the pointed end of each wedge (Fig. 53), is 95 grooved in the direction of the curvature of the outer end of the wedge to receive balls. The cross-section of the pockets 104 is shown in Figs. 47 and 48, which also show the cross-section of the wedge shown in perspective in Fig. 53. The wedges have three walls,—a curved outer-end wall, a flat bottom, and a flat side at right-angles to the bottom. The curved wall has the curved grooves 106 which are eccentric to the axis 105 of the top shaft. That is, the side walls 107 of each slot 106 are concentric with the top shaft axis and are flush with the periphery of the enlargement 103. A sleeve 108 (Figs. 50, 51) has two interior and two corresponding exterior diameters. Portion 109 of the sleeve fits freely on the top-shaft enlargement 103 and holds the wedges 105 in the pockets 104. Section 109 of sleeve 108 is provided with three openings 110 through 115 its annular wall, spaced apart 120° to receive the balls 111, each of which lies in a hole 110, and also lies in a groove 106 of a wedge 105. A ball ring 112 (Figs. 46, 47, 48) forms part of the belt-wheel 113 120 which is made in two parts secured laterally together by screws 114, the ball ring 112 being secured between them. The belt-wheel 113 has a hub 115 projecting from each of its sides, the hub fitting loosely and 125 running on the sleeve 108 which is exteriorly reduced in diameter at 116, 116, and exteriorly provided with an interposed tooth 117 between the portions 116, 116 which are of uniform exterior diameter. The tooth 130

117 is formed by grooving the outer wall of the sleeve annularly and eccentrically to its lengthwise axis between the portions 116 and 116. This eccentric groove is indicated by 118. The interior annular wall of the reduced portion of sleeve 108 has a lengthwise-extending key-slot 119 to receive a projecting key 120 formed on the outer end 121 of the top shaft adjacent the enlargement 103. The interior wall of the reduced portion of sleeve 108 is indicated by 122. The sleeve 108 is provided at the end of its reduced section with a pin 123 extending in the direction of the length of the sleeve. One end of a coil spring 124 is secured to this pin, and the other end of the spring is connected at 125 to the key 120. An end bearing 126 for the sleeve 108 is cut out at 127 and also at 128 and is formed with a bore 129 (Fig. 57) wherein the reduced section 116 of the sleeve freely rotates. A brake-shoe 130 (Figs. 54 and 40) is mounted in the cut-out 127. The shoe has a lining 131 of babbitt or other metal or material, and on its upper or back side has a slot 132 which receives the end 133 of a pressure-plug-lifting lever 134 (Figs. 56 and 40) which at 135 is pivoted in a housing member of the stop-motion and has an extended arm 136 for its actuation. The top of the brake shoe is concaved at 137 at right-angles to the slot 132 to receive the convex head 138 of the pressure-plug 139, the head being slotted at 140 to receive the end 133 of the lever 134. A coil spring 141 surrounds the upwardly-extending stem of the pressure-plug 139 and a hollow screw 142 surrounding the stem of the pressure plug is mounted in the housing member mentioned to regulate the pressure of the spring the under end of which bears on the flange of the head. The housing mentioned is indicated by 143 and is centrally chambered to receive the bearing 126 for the assembled sleeve 108 and shaft end 121 (Figs. 46, 49, 50 and 84). The housing on its side opposite the pressure plug or on its under side in the form shown, has a radial slot 144 which communicates with a slot 128 formed in the bearing 126 and which, adjacent the pressure-plug, is slotted at 145 to receive the lever 134 which at 135 is pivoted between side walls of the slot. The housing 143 is a cylinder in the form shown, and the slots referred to are through its side walls (Figs. 40 and 5). The housing has a chamber 146 at its outward end (Figs. 84 and 5) for reception of lubricant from the oil tube 147, the upper end of the oil tube 147 overhanging and discharging into an oil-feed opening 148 formed vertically in the upper wall of the housing. The lower end of the oil-feed opening 148 communicates with the chamber 146.

65 *Constructional features to facilitate lubri-*

cation and access to stop-motion and the drive therefor. Looper-shaft construction.— The rear side wall of chamber 146 is provided with an oil overflow outlet 149. The outer end of the housing 143 is provided with a recess 150 (Fig. 84) for reception of a transparent end-plate 151 through which the lubricant in the chamber 146 may be observed. The rear end of the housing is formed with a flange 152 which is secured to the rear end wall of the sewing-machine trunk 71. Above the stop-motion (Fig. 5) the trunk 71 forming a part of the top arm of the sewing machine is provided with an opening 153 covered by a removable plate 154. The opening 153 affords access to the stop-motion and other parts. The rear end of the tube 82 in the top arm 69 is provided with a sheet-metal cap 155 having a projection 156 whereby the cap can be shifted endwise to uncover the looper-actuating cranks 101, 102, the cap being provided with an indented catch 157 that engages with a recess in a wall of the tube 82 to hold the cap in its working position shown in Fig. 84. The bottom of the cap 155 is lengthwise split at 158 so that it fits on the tube 82 under tension and the cap is also formed with a downwardly-extending oil drip point or leader 159. The cap has a rear end wall 160 formed with an opening sufficient to permit the cap to pass over the forward flange 161 (Figs. 46 and 84) of the clutch-wheel 113 when the cap is shifted endwise. The ball cranks 101, 102 operate respectively in sockets 162 and 163 and downwardly-extending rods 164 connect these sockets with similar sockets 165 at the lower ends of the rods. One of the lower sockets 165 works on a ball end 166 of the bell-crank lever 167 which is rockable on a horizontal journal 168 at right-angles to the top and looper shafts of the sewing machine and is fixed in side walls of the depending trunk 71. The depending arm of the bell crank 167 terminates in a flat circular end 169 which works in a lengthwise-extending slot 170 of the looper shaft 171 that is tubular and provided with a plug 172 secured by a pin 173 in its rearward portion. A coil spring 174 is mounted in the chamber of the looper shaft rearwardly of the plug 172 which forms an abutment for the forward end of the spring. The rear end of the spring abuts on a sliding plug 175 mounted in the chamber of the looper shaft just forwardly of the slot 170. The plug 175 is provided with oil canals 176 running in the direction of the length of the looper shaft. The plug 175 forms an abutment for the forward edge of the end 169 of the bell crank 167. Just rearwardly of the slot 170 the chamber of the looper shaft is provided with a fixed plug 177 pinned in place at 178, the plug 177 forming an abutment for the rear edge of

the end 169 of the depending end of the bell crank 167. The spring 174 is strong enough to keep the plug 175 at all times pressed against the bell-crank end 169, oscillation of which reciprocates the looper shaft endwise. In this movement the ball joint constructions referred to, permit the oscillation of the connecting rods 164. The pin 178 also holds the crank end 169 to the looper shaft and 10 has an integral ball-joint member 180 which works in one of the sockets 165. This particular construction just described, is for compensating wear on the plugs 175 and 177 and the intermediate bell-crank end 169. 15 The looper shaft is mounted loosely in bearings 181 contained within the tube 182. The rear bearing 181 is provided with an oil canal 183 on its under side and extending in the direction of the length of the looper shaft. The forward bearing 181 is provided 20 with an oil canal 183^a extending in the direction of the length of the looper shaft and at a higher elevation than the canal 183. The front bearing 181 has on its front wall 25 an annular recess 184 with which the oil canal 183^a communicates. A plug 185 is secured to the front end of the looper shaft by a pin 186, the plug having an outwardly-projecting stem 187 upon which is fixed a looper carrier 188 provided with a looper 30 189 underneath the throat or needle-hole plate 190 which is secured to the under arm 70 of the sewing machine.

A sewing-machine drive-belt 191 for operating the needle or needles and the looper, runs over the belt-wheel 113 passing down through an opening 192 of the oil reservoir pan 193 which is horizontal and covers the top of the oil or lubricant reservoir 194 located at the bottom of the trunk 71. This reservoir 194 contains an oil pump 195 driven from the belt-wheel 196 on the other side of the reservoir. The up-going run of belt 191 engages the pump's belt-wheel 196 to drive it, and the belt is driven from an electric motor 197 (Figs. 6, 62, and 85-89) having a belt wheel 198 rotating in the direction of the arrow shown in Fig. 86.

The motor's belt-wheel 198 is mounted on 50 the motor shaft 199 which is prolonged (Fig. 6) and journaled in a bearing 200 carried by the depending web 76 of the sewing machine, the motor itself being also carried by the sewing machine. The inward end of the motor shaft is provided with a bevel gear 201 which meshes with a bevel gear 202 on the shaft of the under band-knife wheel 77 to drive the band knife 78. The motor shaft 199 is provided with a 55 quick-coupling device 203 (Fig. 64) to connect or disconnect the shaft and the motor. An electric switch 204 (Fig. 5) is provided for the motor 197.

The stop-motion control.—The sewing- 60 machine trunk 71 is provided with a bulging

projection 205 of its upper front side, the projection extending from rear end to front end wall of the trunk (see Figs. 7, 9, 63 and 40). The front wall of the bulging projection is vertically slotted at 206 (Figs. 62 and 70 40) to receive the hub 207 of the stop-motion control lever 68. This lever is formed forwardly of its hub with a transverse opening 208 into which projects the end of an adjusting screw 209 to engage the end 210 75 of a lever 211, the end 210 projecting laterally into the hole 208 in opposition to the end of the adjusting screw (Figs. 7 and 40). The stop-motion control lever 68 is fixed on a transverse supporting shaft 212 by set screw 80 68^a. The ends of the shaft 212 are journaled in bearings in the wall of the bulging projection 205 and the lever 211 is loosely fulcrumed on this rocker-shaft 212. It is provided with an upwardly and forwardly 85 projecting arm 213, the free end of which overlaps the forwardly projecting arm 136 of the pressure-plug lever 134. The rear arm 214 of the controlling lever 68 projects into the chamber of the trunk and its upper 90 side is recessed at 215 to hold a wire basket or the like 216 filled with filtering material 217, the basket or container being held in place by a staple 217^a. The recess 215 and filtering material hold lubricant supplied 95 by the oil pump referred to. An oil canal 218 extends forwardly from the bottom of the lubricant recess 215 through the end wall of a bore 219 in the rear end of the controlling-lever arm 214. The outer portion 100 of this bore is tapped to receive a hollow annular bushing 220 having in its inner end a plug 221 secured to the bushing by a transverse pin 222. The plug has an integral rearwardly-extending stem 223. The outer 105 or rearwardly-extending end of the bushing is threaded so as to be screwed into the tapped end of the bore 219, and inwardly or forwardly of its threaded portion the bushing has a reduced exterior diameter through 110 the side walls of which, just inwardly of the inner wall of the plug 221, oil holes 224 are formed. The annular wall of the bushing also has a series of annularly arranged oil holes 225 adjacent the inward end of its 115 threaded portion. A sliding thimble 226, the closed end of which is rounded off at 227 is mounted in the bore of the bushing 220, the tubular wall 228 of the thimble sliding freely in the bushing, and serving as a valve 120 to cover and to uncover the series of oil holes 225, but not to cover or uncover the oil holes 224. A coil spring 229 surrounds the plug stem 223, abuts against the outward or rear wall of the plug, and also abuts 125 at its other end against the end wall of the thimble, and this spring has a strength just sufficient to push the sliding thimble outwardly to uncover the oil holes 225 when exterior pressure on the thimble end is re- 130

lieved. The outwardly-rounded head 227 of the thimble is always pressed outwardly by the spring 229 against the opposed end 230 of a stop finger 231 which at 232 is pivoted to a bracket carried by the rear end of the arm 214 of lever 68. The lower end of the stop finger is provided with a transverse pin 233 (Fig. 41) projecting on both sides, and each projecting end of the pin has connected to it a coil spring 234. The upper end of each spring is attached to the projecting neck ends 235 of the fulcrum pin 232. The springs thus mounted are under tension and hold the stop finger 231 with the pivot pin 232 abutting against the under wall of a slot 236 formed through and elongated in the direction of the length of the stop finger, by the spring 234 and slot 236 construction. The finger 239 permits the levers 68 and 214 to assume the position shown in Fig. 40 even if the tooth 117 is not in exact position for reception of finger 239 so that it will enter the eccentric cut to engage the tooth 117 on its next rotation. The bracket 237 carried by the lever arm 214 is slotted at 238 to receive the stop finger, the head 239 of which coacts with the stop tooth 117. The upper side of the bracket 237 projects upwardly into a slot 143^a of the housing 143. The mode of operation of the stop-motion mechanism for each top shaft of the sewing machines is described below, as is also the constant supply of the oil recess 215 and the moving parts of the stop-motion mechanism with oil from the oil pump. And I consider a body of oil or other lubricant contained within the thimble 226 and the bushing 220 and the plug 221, as a vitally-important feature of and factor in the stop-motion mechanism. This body of oil which I show in Fig. 40 by dots marked C, constitutes a shock-absorbing cushion, which cushion is characterized by the power to absorb shock without any resultant rebound.

The stitching mechanism.—A stitching mechanism in slightly different forms is shown in Figs. 62 to 75 inclusive, Figs. 68 to 73 showing specifically a mechanism for making the well-known two-thread-chain-stitch (see also Figs. 62 and 63). Figs. 74 and 75 illustrate a certain variation of the mechanism for making the two-thread-chain-stitch, practically involving a duplication of some parts whereby the mechanism is specifically designed for making two lines or two rows of two-thread chain or double chain stitch. The single needle 92 used in making the two-thread chain-stitch, and having the usual reciprocating vertical motion, carries a needle thread 240. A loop 241 is thrown out in the usual way and is entered by the looper blade 242 which carries the looper-thread 243 and presents a loop 244 of this thread for the needle on its next descent to form a stitch. Referring

now more particularly to the two-line or double chain stitch mechanism (Fig. 74), it comprises a looper carrier 188 provided with two sockets 245 spaced apart and holding the looper shanks 189. The looper blades 242 operate one at one side and the other at the other side of the band-knife slot 246 in the throat or needle-hole plate, 247. A vertical U-shaped guard 248 which encloses the cutting run of the band knife adjacent the stitch-forming instrumentalities, is provided to prevent the band knife from contact with the needle and looper threads. This guard depends from the throat plate and also serves as a protection for the operator's fingers in threading the loopers. The throat plate is secured to the machine base 70 and is provided with needle-guards 249 on its under side, these needle guards each having a needle hole 250. The needle holes 251 in the throat plate register with the needle holes 252 in the foot 253. This foot occupies a position relatively to the needles and throat plate of an ordinary presser foot, but differs therefrom in that it exerts no downward pressure on the goods. It may be called a gliding foot because it glides over the goods in the travel of the machine or machine heads instead of forcibly impinging on the goods as is the case of a presser foot in an ordinary non-traveling sewing-machine or the like. Its purpose is to prevent the goods, while they are being fed, from lifting with the needles. Sometimes there is a thick part of the goods being fed through, and this foot may be lifted by the thick part of the goods during the feed movement thereof. This foot is slotted from its front end about midway between its sides at 254 for reception of a run of the band knife and has its free ends 255 upturned. It is provided with a needle guiding wall 256 which extends transversely across the upper side of the foot just rearwardly of the needle holes 252. The purpose of the needle guard is to form an abutment for the rear sides of the needles when they are in the goods, to minimize the rearward breaking strain thereon due to the pull of the goods rearwardly in their feed movement. This foot 253 is secured to a shank 257, conveniently by a screw 258, the shank having a socket 259 whereby it is attached to the foot-support 260 by a screw 261. The shank 257 has a portion 262 rising above and projecting forwardly over the foot-support, and this portion 262 is tapped to receive an adjusting-screw 263 provided with a lock nut. The under end of the adjusting-screw bears on the upper edge of the foot-support, and adjustment of the screw regulates the position of the foot to the work thereunder. The contact of the screw and foot-support is indicated by 264. The foot-support has a vertical extension 265 secured to the ma-

chine frame at 266 (Fig. 63). A spring 267 is interposed between shank 257 and the foot-support to give downward pressure to the foot 253. For convenience I have indicated the needles in the two-line or double chain stitch arrangement of Fig. 74 as 258. Each is carried by the double needle-holder 269 which is provided with a lateral projection 270 provided with holes to fit on the 10 guide-bar 93. In the single needle-holder shown in Figs. 65 and 66 there are two tongues 94 spaced apart in a vertical direction. The double needle-holder shown in Fig. 74 is provided with the same laterally 15 projecting tongues 94. In the structure of Fig. 74 a needle-thread nipper 271 is pivoted at 272 between the forwardly-projecting parallel vertical lugs 273 formed on the front side of the needle-holder. These lugs 20 273 are disposed one adjacent a projection 270, and the other laterally removed therefrom nearer the free end of the needle-holder. These projections 273 are provided above and below the pivot pin 272 with 25 alined needle-thread-guide holes 274^a. The free end of the needle-holder is provided with a forwardly projecting lug 273^a corresponding to the lugs 273. This lug is provided with a needle-thread hole 274^a. The 30 thread for the inside needle, the one nearer the thread-nipper, passes through the under holes 274^a, and thence to the needle. The thread for the outside needle goes through the upper thread-holes 274^a and through the 35 thread-hole 274 in the projection 273^a to the outside needle. The needle-driving link 89 is attached to its under part at 275 a needle-thread nipper spring 276 which depends rearwardly of the thread-nipper 271, 40 the upper needle-thread passing directly between the spring and the upper arm of the pivoted thread-nipper, and the under thread passing directly between the spring and the under arm of the pivoted thread-nipper, 45 so that both needle-threads 240 may be nipped with equal pressure. The operation of the thread nipper is set forth below. Each looper thread 243 is conducted through a tube 277 (Figs. 5 and 74) having a slot 278 50 throughout its length for threading, the thread leading from the tube to a thread tension 279 secured to an angle-bracket 280 fast on the frame 70. The tension is intermediate the tube and the looper. When a plurality of threads and loopers are used there 55 will be a tube and tension for each looper-thread. In connection with the single-line stitch mechanism, the needle-holder 91 (Figs. 65 and 66) is provided with a needle-thread guiding-tube 281 cut out at 282 opposite the nipper spring 276 so that the latter may pinch the thread as it passes through the tube against the wall of the tube. 60 The tongues 94 of the needle-holder in a 65 groove of the needle-holder guide 96 pre-

vent the needle-holder from rocking laterally during its vertical reciprocatory movements, and the dependent guide comes well down toward the throat plate so that the needle thrust through the goods is as nearly 70 adjacent the under end of the guide as working conditions practically allow. Hence the needle is steadied in its thrusting movements down through the goods.

Over-stitch mechanism.—In some or all 75 classes of work done by this combined cutting-and-sewing machine it may be desired to employ over-stitch-forming mechanism rather than either of the chain-stitch-forming mechanisms described,—and just as 80 either a single needle or a plurality of needles may be employed in connection with the pivoted link or pitman 89, so also over-stitch-forming mechanism suc has shown in Figs. 76 to 83 inclusive, may be used in connection therewith, the single needle for each 85 sewing-machine head being in the latter case carried by a needle-holder such as shown in Figs. 65 and 66, the needle-holder working on the dependent guide-bar 93, and 90 the slotted needle-holder guide 97 as already described. Referring particularly to Fig. 78, the additional parts coöperating with the needle and said actuating mechanism, and required for formation of the over- 95 stitch mechanism, are now about to be described, it being noted that my over-stitch mechanism does not require the coöperation therewith of an oscillating looper such as 100 189 already described and which may be removed from the machine when the over-stitch auxiliaries are mounted therein. These auxiliaries or parts are,—a link 283 pivotally connected with a crank-pin 88 at one end, and at its other end pivotally connected 105 at 284 with one arm of a bell-crank lever 285 the other arm of which is pivoted at 286 to a bracket 287 on the sewing-machine head. Between its ends the bell-crank 285 is pivotally connected at 288 to a downwardly-extending link 289 the lower end of which is pivoted at 290 to the lower end of a lateral link 291 the upper end of which is pivoted at 292 to a bracket 293 which is a lower 110 and divergently-extending portion of the 115 bracket 287. The upper end 294 of the looper arm 295 is journaled on the pivot stud 290, being interposed between the lower end of the link 289 and the lower end of the link 291. This looper arm is pivoted at 120 296 between its ends to a link 297 which is pivoted at 298 to the bracket 293, but at a point below and nearer the needle than the pivot 292. The looper stem or portion below its pivot 296 is indicated by 299 and its 125 lower end 300 is formed as a finger the purpose of which is to project into a space formed by cutting the goods and to remain between the walls of such a cut to keep the

wall of the edge being stitched from getting in the path of the looper jaws 301, 302 which are rigid lateral projections of the looper stem, projecting therefrom through the path 5 of the needle. This is illustrated in Fig. 77 where a slit in the goods caused by the band knife 78 is illustrated. The bracket 287 carries a needle-holder guide 303 for the needle-holder 91.

10 The looper device of this over-stitch mechanism is mounted and operated at an angle to the feed of the material 304 slit at 305 by the band knife 78 which operates sufficiently in advance of the needle to permit 15 the looper jaws 301, 302 to operate between the rear edge of the needle and the needle in order to seize loops of needle thread 306 underneath the throat-plate tongue 307, drawing said loop out as shown in Fig. 81 20 so as to cast the same around the lower jaw 302 as shown in Fig. 82. The looper jaw 301 is the primary needle-loop-receiving jaw, and the jaw 302 is the thread-carrying jaw, but in casting the loop on the lower jaw 302 25 the thread comes from the jaw 301, all of which will be readily understood by those skilled in the art as the arrangement of the looper jaws and the needle here shown are of themselves old and well-known; but in 30 the present case I have turned the old looper mechanism in question upside down and reversed the relation of the jaws one to the other and provided the looper stem with the finger 300. However I am the first so far 35 as I know to locate this old over-stitching mechanism above the throat-plate and consequently above the work-plate, and to provide means for making it coöperate above the work with the needle. But it is also to be 40 said that in my present arrangement, while the looper jaws reciprocate between a position above and a position below the throat plate, they also reciprocate through the slot or opening 305 formed in the goods by the 45 cutter 78. In the present construction (Fig. 78) the looper stem is laterally offset below its pivot 296, and the looper is mounted as already described, on the forwardly and outwardly-projecting bracket 293. The result is that the looper jaws extend toward the needle diagonally to the line of cutting by the band cutter 78, and to the line of stitching performed by the machine in which this looper mechanism is embodied. The 50 diagonal relation is indicated in Fig. 77. The purpose of this arrangement is at all times to keep the looper as close to the edge of the slot in the goods that is being stitched as feasible; to cause the looper jaws to move 55 into a position behind the needle when below the throat plate; to move into a position in front of the needle when above the throat plate to properly form the stitch; to secure a minimum projection of the looper 60 jaws at one side of the path of the cutting 65

run of the cutter 78 as is feasible in order that the opposite edges of the slot 305 may be required to be separated a minimum distance. The V-shaped character of the cut shown in Fig. 77 is due in part to the springing apart of the cut edges as they are formed, and in part to the lateral vibration of finger 300 between their edges, the finger tending to push them slightly one way or the other, or by the independent action of the 75 goods or of the finger 300 according to the character of the goods acted upon. Tubular knit goods when slit after being distended on the spreader, spring apart at the cut edges to a considerable extent. Flat goods on the 80 other hand would have the cut edges separated more particularly by the vibration of the finger 300. As the looper rises, the needle-thread loop slides back on the jaw 302 to the position shown in Fig. 82, at 85 which time the looper thread 308 carried by the looper jaw 302 lies at an angle extending from the throat-plate tongue 307 to the front eye of the looper jaw 302, forming a triangle so that the point of the needle may enter 90 between the looper jaw and the thread and draw the looper thread down on the upper surface of the work as indicated by 91 in Fig. 83. As the looper moves outward and downward, the needle loop 306 drops from 95 the end of the looper jaw 302 so as to form the stitches 311 (Fig. 77). While the looper thread 308 forms the beaded edge 312 of the seam, the movements of the looper are such that the finger 300 always remains within 100 the slot 305. The looper mechanism is so timed in relation to the reciprocation of the needle that the looper is slightly slower in its movements than the needle is in its movements, and this difference in speed or timing 105 permits the needle to deflect the looper needle thread as shown in Fig. 80, while the looper jaw 301 is entering the loop. Consequently the needle is rising ahead of the looper and starts to descend so that as the looper jaw 110 302 reaches the position shown in Fig. 83 the needle enters the loop of looper thread to complete the formation of the stitch. In this case the throat plate 313 has a slotted 115 needle-hole 314, and the foot 255 also carries a tongue 315 over which the stitches are formed, the slotted needle-hole and foot tongue-structure being known in over-stitch mechanism.

The thread-handling or pull-off mechanism, (Figs. 5, 18 and 74.)—The needle thread 240 passes from the needle through the tube 281 and is led between the nipper spring 276 and the wall of the tube 282; thence through the eyelet 316 to and through 120 an eyelet 317, whence it is led through an eye 318 in an end of the trip-lever 370; thence through an eye 319 of the thread pull or measuring lever 421; thence passing between tension-disks 320; thence through an 125 130

eyelet 321; thence through an eyelet 322; and through an eyelet 323 to the thread-stand eyelet 324; thence to the thread-stand tension 325 and to the supply 326 carried by an arm 327 of the sewing-machine trunk 71.

The looper thread 243 passes from the looper jaw 242 to the tension 279; thence through the thread-guide tube 277; thence through an eyelet 277^a under the needle-thread eyelet 323; thence through the eyelet 324; thence to a tension 325; and thence to another supply carried by the thread stand.

In order to start and stop the sewing of either of the two sewing machines rapidly and automatically it is desirable to break the needle and looper threads at the end of each stitching operation in the formation of a given article, and to leave the thread ends extending sufficiently through the eyes of the needle and looper to insure positive resumption of sewing immediately on the re-starting of the sewing machines to sew. Therefore I provide mechanism to measure off sufficient needle and looper thread each time the machine is stopped automatically at the completion of the stitching of a product, at which time the threads are broken close to the work. At the same time parts under the control of the needle-thread are held against action in order to prevent the automatic stop-mechanism of the machine in its entirety from stopping the goods-feeding devices. It is noted that when the threads break by accident, or the stitching fails for any reason whatever, provision is made for thereupon instantly stopping the machine in its entirety, the travel of the sewing machines and the stitching operations of each thereof being then arrested as an incident of the stopping of the machine in its entirety. But the point under immediate consideration is the mechanism for breaking the thread close to the work when a sewing machine is stopped automatically at the conclusion of its normal sewing of a machine product, such automatic stopping being effected by the clutch motions for the sewing machines under control of cams carried by the master cam. To break the thread close to the work a link 329 pivoted at 52 to the lever 55, is provided with a spring 330, one end of the spring being attached to the frame 58, and the other end being attached at 54 to the link 329 (Fig. 5). The action of the spring which is shown as a coil spring, is to pull the link 329 inwardly in the direction of the pattern cam and better hold the roller 60 on the pattern cam. A coil spring 331 is attached at one end to the frame 58, its other end being attached to the link 49, and the tension of this spring pulls the link 49 endwise inwardly so that its cross pin 49^a bears against the outward edge of the frame 58. Pin 49^a constitutes an arresting device against the frame 58 as an abutment to prevent the slot 53 in the inward end of the link 49 from striking against the pivot pin 52 so that the pivot pin 52 may shift laterally outward in the slot 53 when the roller 60 mounts the first step 63 (Fig. 10) of the cam 62, without giving outward endwise movement to the link 49. If such outward movement were given to the link 49 there would be a tendency to start the sewing machines before the thread-breaking devices properly operated. The outward end of the link 329 is pivoted at 332 to the downward-extending arm of the bell-crank lever 333 which is pivoted at 334 on a pin 335 fixed on the front wall of the machine. The other and outwardly-extending arm of this bell crank has pivotally secured thereto at 336 a track 337 for supporting a slide member, described below, of the thread-breaking and thread-measuring mechanisms. This track is also, inwardly of its pivotal connection at 336, pivotally connected at 338 with an outwardly-projecting arm of a bell-crank lever 339 which is pivoted at 340 to the front wall of the frame (Fig. 7; see also Figs. 5 and 10). The downwardly-extending arm of the bell-crank is pivotally secured at 341 to a link 342 which extends outwardly and pivotally connects at 332 with a downwardly-extending arm of the bell-crank 333. When the link 329 is moved endwise outwardly, the bell-cranks 333 and 339 are rocked to raise the track 337. In Fig. 10 the track 337 corresponding to the left-hand sewing-machine is shown in its lowest position, and in the right-hand portion of Fig. 10 the track is shown in its highest position. The opposite ends of the master cam are each provided with one of the cams 62, and one of these cams is on one side of the master cam and the other is on the diametrically opposite side of the master cam. In practice the master cams are provided with the peripherally-projecting cams 62 variously located with reference to one another and to the pattern grooves of the cam according to the shape of the pattern grooves which correspond to the pattern to be cut and stitched. Just what the relative positions of the master cam and the two cams 62 will be in a given case will depend entirely on the nature of the work being produced. In some cases it may be desirable, for example, to stop the stitching at knee, and in other cases at the hip or crotch or ankle, and therefore the cams 62 are accordingly fixed on the master cam. A slide block 343 moves on the track 337. The non-working run of the band-knife runs preferably through a portion of the machine (Fig. 8) which would make it inconvenient to put on and take off the band-knife were it not for the provision of the quick coupling between the slide 343

block 343 and the upwardly-extending arm of a bell-crank lever 347 for actuating the thread-measuring mechanism.

Pivoted to the block 343 at 344 there is a coupling 345 (Fig. 15) which sets in the recess 346 of the under arm of a bell-crank lever 347 which is pivoted at 348 (Figs. 11 and 5) to a bracket 349 fixed to the machine base 70. A yoke 349^a having a transverse rib 349^b on the under side of its crown, straddles the lower arm of the lever to hold the coupling in the recess, the rib 349^b resting in the transverse recess 349^c in the upper edge of the under arm of this bell-crank, and the spring 350 pressing downwardly on the crown of the yoke. The coupling forms a loose joint. This construction permits the coupling 345 to be swung into an inoperative position (Fig. 15) for passage of the outward run of the band-knife when it is put in place or removed. The pivot 344 (Fig. 14) is a shouldered screw, and between the head of the screw and the coupling 345 there is a coil spring 352 around the outwardly-extending portion of the screw forming pivot 344. This spring presses the coupling laterally into its slot 346 and also against the slide block 343. The dotted line position 351 (Fig. 15) shows the coupling when it is detached from the lower arm of the bell-crank 347. The bell-crank 347 has an upward arm 353 to which is pivotally secured at 354 a link 355. The inward end of this link is pivoted to a rocker arm 356 (Fig. 59) of a rocker shaft 357 mounted in the tubular bearing 358. The rocker arm 356 has a segmental shaped end 359 beveled at 360 (Fig. 59) to coöperate intermittently with the beveled edge 361 of the conical collar 362 which is adjustably secured to the rod 363 which is endwise movable in the bearings 364 which also support the tubular bearing 358. The outward bearing 364 is formed with a vertically-slotted hole 365 for passage of the rods 363, and a spring 366 has one of its ends fixed at 367 to said outward bearing 364, this spring being shown as a wire spring having a turn between its ends whereby its end fixed to the collar presses downwardly and also in the direction of the arrow shown in Fig. 59. The other end of the spring is fixed to the collar 362 at 368. The collar is fast on the slide rod 363, and the tension of the spring holds the collar 362 against the bottom of the vertically elongated slot 365 so that the inward edge of the bevel 361 may be in the path of the edge of the bevel 360, and at the same time the tension of the spring presses the rod 363 inwardly in the direction of the arrow shown in Fig. 59, the opposed margins of the collar 362 and of the segment 359 then being pressed against each other. The rod 363 is also provided with a fixed spool-shaped collar 368 (Figs. 59, 61) coöoperating

with a forked end 369 of the thread-actuated lever 370 which is pivoted at 371 to the back plate 372 which carries the bearings 364 and the mechanism in question, and is attached to the front side of the top arm of the sewing machine (see Figs. 5 and 58). The lever 370 has an upwardly-curved free end 373 in which is pivoted at 374 one or more thread eyes 375 that project from its end. The eyelet 318 is rigidly secured to the up-turned end 373. As shown in Fig. 59 there are two of the thread eyes 375 pivotally secured at 374 for use in connection with the two-line stitch mechanism above referred to. In Fig. 10 the thread eyes 375 are shown in horizontal position at the left-hand of the figure, while at the right-hand of the figure the thread eyes are shown in vertical position.

Thread-controlled electric stop-motion.—
The upper arm of a bell-crank lever 376 bears against the outward end of the rod 363, the bell-crank being pivoted at 377 to a bracket 378 carried by the trunk 71 (Figs. 5, 11, 58 and 59). The lower arm of lever 376 carries an insulating block J at the free end of which is a contact I which is adapted to make and break electrical connection with an electrode G carried by an insulator 379 fixed to the bracket 378. The upper wall of this bracket is provided with holes 380 for attachment of the bracket to the trunk 71. The insulator 379 is also provided with an electrode G' from which a lead H extends to the contact I. Preferably the lead H is bow-shaped, the crown of the bow extending back of the pivot 377 so that the under arm of the bell-crank may have very easy movement without encountering much resistance in its vibration. The sewing-machine supporting track 381 is provided with lengthwise-extending conductors F, the electrode G' riding against the upper conductor F and the electrode G riding against the under conductor F. The conductors F are insulated from the track 381 by insulation blocks or pads 382 (Fig. 16), the track being supported by the back section 383 of the machine frame (Figs. 16 and 17). The upper edge of the track constitutes a guide for the sewing machines in their travel, the bottom of the sewing-machine base being lengthwise grooved at 384 (Fig. 7) to fit on the track. The sewing machines are also supported by track 75 extending transversely of the machine underneath the track 381.

Referring now to the slide 343 of which there are two, each operating on a track 337 for each sewing machine, and which pertains to the looper-thread-breaking mechanism, said slide has pivoted to it at 385 one end of a lever 386. The other end of this lever (Figs. 14, 9 and 10) is fixed to one end of a rock-shaft 387 mounted in bearings 388

secured to a web 389 integral with the web 72 of the sewing-machine frame and at right-angles thereto, the web 389 forming the rear end wall of the sewing-machine frame. The other end of the rock-shaft 387 is provided with an up-standing arm 390. The upper end of the arm 390 has pivoted to it at 391 (Fig. 10) a horizontally-extending rod 392 which, by means of a coupling 393 used for convenience of assemblage, is connected with an extending rod 394 slidable endwise in a bearing 395 in the sewing machine base. The inwardly-projecting end of rod 394 is provided with a roller 396 which operates in an elongated slot 397 formed in the lower end of an angle lever 398 which is pivoted at 399 to the throat-plate 190. In Fig. 10 I have shown the rod 394 broken in order that the two throat-plates shown might be put in plan view for convenience of illustration. In reading this figure it is to be understood that the angle lever 398 and the throat plate are horizontal. One arm of the angle lever 398 projects opposite the rear edge of the throat-plate, and pivotally secured at 400 to such end of the angle lever 398 there is the thread-breaking slide 401 which is used to break the bottom thread which, as shown in the present drawings, is the looper thread. The bottom thread might of course come from a shuttle if a lock-stitch machine were used. In the present case the bottom-thread breaker slide 401 breaks the looper thread at the upper side of the throat-plate close to the under side of the work, the top or needle thread being then broken by the pull of the main feed-rollers on the goods straining the top thread at a looped portion thereof around the looper 242. The looper-thread breaking slide has its front end 402 made wider than its shank portion (Fig. 68), and this front end is provided with a needle hole 403 which is elongated rearwardly to form a slot 404. This needle hole registers with the needle-hole 251 in the throat-plate 190 which is milled out lengthwise on its upper side to receive the breaker slide 401 and permit the same to reciprocate therein with its top surface flush with the upper surface of the throat plate. A plate 405 secured to the upper side of the throat-plate at 406 has its inward margin reduced in thickness at 407 where it overlaps the upper side of the breaker-slide 401 (Figs. 68-73). Between its ends plate 405 has a transverse vertical wall 408 formed by cutting out or thinning the front end of the plate 405 to form the forwardly horizontally-projecting lip 409, the under surface of which is spaced above the top surface of the throat-plate to form a clearance for the bottom thread when the slide 401 reciprocates, then having the bottom thread pass through its needle hole. The wall 408 is located back of the needle-hole in the breaker slide sufficiently to permit a long end of looper thread 243 to be pinched between it and the upper surface of the breaker slide as at 410 (Fig. 72). The front edge or end 411 of the lip 409 is beveled upwardly and outwardly (Fig. 71), and when the bottom thread 243 is broken, it extends through the front thread eye of the looper 242 upwardly through the needle-hole in the throat-plate (Fig. 72) across the throat-plate, thence through the eye of the thread-breaker slide 401, thence forwardly over the front margin of the lip 409, to the goods. The plate 405 has a slight spring action. After the bottom thread is broken by strain on the goods pulling such thread over the edge 411, the free end of the bottom thread remains in the clearance referred to until another stitching operation is about to begin. A small projection 412 on the upper side of the throat-plate rises past the clearance between the lip 409 and the throat-plate and serves to prevent threads or the goods from being accidentally caught under the projecting end of lip 409. The cutting run of the band-knife operates in a vertical dependent knife-guard carried by the throat-plate (Fig. 70). This is located at the inner side of the bottom-thread-breaker slide, and its upper portion 413 comes above the clearance space referred to, so that the upper portion of the band-knife guard 414 serves to prevent goods and thread from getting accidentally into said clearance space, and also keeps out lint therefrom. The inner edge of the throat-plate 190 is bent down at 415 to prevent goods and thread from catching on the throat-plate. This action of the bent-down inner margin of the throat-plate is due to the fact that in the machine in question, the goods are being fed flatwise from the front tensioning devices to the main feed-rolls, and consequently if there is a hole in the goods and such hole is approaching the stitch-forming instrumentalities, the bent-down end is not liable to catch into the hole and arrest the forward progress of the goods. The throat-plate 190 is provided with a hole 190' rearwardly of its needle-hole to give freedom of movement to the bottom thread when it is in the position shown in Fig. 72. The rocker shaft 387 (Figs. 10, 59 and 60) has fixed to it a hollow rocker-arm 416 in the chamber of which there is mounted a coil spring 417 inclosing the shank of an endwise-movable latch 418 provided with a stop-pin 419 which passes through an elongated slot of the chambered arm. The outer end of the spring latch 418 coacts with the end 420 of the needle-thread measuring lever 421 which is pivoted at 422 to the plate 372. The forward end of this lever 421 passes back of a needle-thread tension de-

vice 320 which carries the needle-thread eyelets 319. This tension device is a special form devised by me with particular reference to the thread-handling mechanism, 5 and comprises a pair of upwardly-extending spring plates 423, one of them carrying a laterally-projecting pin 424 which passes through an opposed enlarged hole 425 to prevent the thread from jumping out from between the plates. The lower ends of the 10 two plates are notched to receive a pin 426 projecting from the front face of the plate 372 and preventing the plates from turning on the tension-post 320^a which is fixed to and projects forwardly from the plate 372.

The breaker slide 401 also serves as a looper thread pull-off or measuring slide. The looper thread, in consequence of the 20 rearward movement of the breaker slide 401, is broken over the front edge or end 411 of the lip 409, the needle thread being simultaneously broken across the under edge of the looper blade in consequence of the rearward pull on the goods by the feed rolls. 25 When the looper thread is broken, as stated, a portion of it has been just previously pinched between the upper surface of the breaker slide and the transverse vertical 30 wall 408 of the plate 405.

Auxiliary cutting devices.—In order to produce a large variety of work I have provided the machine with several cutting devices in addition to the usual band cutters.

35 I provide a jig-knife cutting attachment. Where cutting operations are to be discontinued at intervals I remove a band-knife and mount a jig-knife attachment. Thus in Fig. 35, a jig-knife-holding bracket 427 is chambered at 428 to fit on the looper shaft-casing 182 to which the bracket is secured by a set screw 427^a. A bell-crank lever 429 is pivoted to the bracket at 430, its upper arm being connected with one end of 40 a horizontal link 431 by a pivotal connection 432. The jig-knife 433 having a hooked end is pivoted to the front end of link 431 at 434 and is formed with a cutting under edge 435. The shank of the jig-knife extends 45 downwardly and is pivoted at 436 to the horizontal lever 437 which is pivoted at 438 to the upper end of a jig-knife controlling-rod 439 which is under the control of the master cam through cams carried by it. The other 50 end of lever 437 is jointed at 440 to the upper end of a downwardly-extending pitman 441 which has a connection at 442 with a crank 443 of the actuating wheel 448. The outer end of the lower arm of the bell-crank 55 429 has a jointed connection at 444 with the downwardly-extending pitman 445 which has a joint connection at 446 with a portion 447 of the crank 443 which is a two-throw crank. The wheel 448 (Fig. 39) 60 comprises a side plate 449 secured to one side

of a hollow-centered disk 450. This disk is centrally bored at 451 to form a loose bearing on the shaft 452 which is tubular. The disk is formed with a number of transverse bores 453 forming oil chambers. The 70 chamber 454 of the shaft forms a portion of an oil conduit. The shaft is reduced at 455 where it is secured in one end of a swinging arm 456. The reduced end of the shaft has an oil cup 457 attached to it. Arm 456 is 75 pivoted (Fig. 5) at 458 to the bracket 427. The bracket holds the periphery of the wheel 448 in the path of the periphery of the lower band-knife wheel 77 whereby rotation of the lower band-knife wheel 80 rotates the wheel 448 for actuation of the jig-knife. An eccentric 459 having its shank 460 secured to the bracket 427 by a nut 461 affords a means of pressing the periphery of wheel 448 on the periphery of the band-knife wheel 77. Band-knife wheel 77 in giving rotary motion to the wheel 448 actuates the pitmans 441 and 445 and the levers 437 and 429, thereby giving movement to the hooked end of the jig-knife in an 85 approximately oval path as indicated by any one of the diagrams A', B', and C' shown in Fig. 34. To facilitate the cutting action of the hooked end of the jig-knife 90 433 I provide a flat knife 462 which is secured in the needle-guard 249 by a clamp 463. This flat knife has its cutting edge extending upwardly into a slot 464 of the throat-plate 190 (Figs. 36 and 37) and is confined in coöperating position with the 95 cutting edge 435 of the jig-knife by a portion 465 of the throat-plate.

The rod 439 is guided in an upper bearing 466 and under bearing 467, the bearing 466 being a part of the bracket 427 and the bearing 467 being carried by an arm 468 of the web 78. The lower end of this rod is bent laterally at 469 and fits into a slide-block 470 which operates in a horizontal groove 471 of a bar 472 extending transversely 100 of the machine (Fig. 6). This bar 472 may be called the jig-knife-actuating bar and it is pivotally connected near its opposite ends as at 473, 473^a to the arms 474 of a rock-shaft 475 which is mounted in a 105 bracket 476 fixed to the frame wall 58. One of the arms 474 carries a roller 477 which acts upon a cam projection 478 carried by the master cam for the purpose of rocking the shaft 475 and of lifting the bar 472 and thereby moving the rod 439 for projecting the hooked knife 435 so as to cut in any one of the oval paths A', B', C' shown in Fig. 34, that may be desired, the cutting position 110 of the jig-knife depending upon the height 115 of the cam projection. When the roller 477 is resting on the master-cam periphery (Fig. 7^a), the cutting blade 435 operates in the path A' (Figs. 34 and 31). As the 120 roller mounts the step 478^a (Fig. 7^a) the 125 roller

knife 435 operates in the path B'. And as the roller mounts the step 478^b the knife operates in the path C'. In Figs. 34 and 31, A' indicates a movement of the cutting end 5 of the jig-knife below and out of the goods, the jig-knife when used, constantly moving even if it is not cutting goods; B' represents the knife cutting through the under wall of distended tubular goods; and C' 10 represents the knife cutting through both the under and the upper walls of distended tubular goods.

A spring 479 (Fig. 6), one end of which is attached to the bracket 476, and the other 15 end of which is attached to the shaft 475, tends to rock the shaft 475 so as to throw the under end of the rocker arm 474 toward the master cam and thereby press the roller 477 against the master cam and the 20 projecting cam surfaces.

Side-slitting devices. (Figs. 23-27.)—The machine is shown provided with two side-slitting devices. The description of one will suffice for both. Each comprises an 25 electric motor 480 to which a lead wire 481 extends. A disk-knife 482 provided with a guard 483 is attached to the motor shaft, the guard being attached to the hub 484. The guard is cut away at 485 to permit the 30 disk-knife 482 to enter between the plates 486 carried by a tubular goods-spreader such for example as shown in my said allowed application a portion of which is shown herein and marked 487. The motor 35 is fixed to the upper end of a vertical shaft 488 (see also Fig. 7). This shaft has a reduced portion 489 mounted in a bearing in the bracket 490 which is provided with a dove-tailed groove 491 along its back side 40 to fit on the dove-tailed rail 492 that extends horizontally and is fixed to the machine frame. Clamp screws 493 hold the bracket in adjusted position. The under portion of the bracket is provided with a longitudinal 45 bearing 494 carrying a rocker shaft 495. This shaft carries a fixed bevel-gear 496 which meshes with a bevel-gear 497 fixed to the reduced shaft portion 489. A crank 498 is fixed to a portion of the rocker shaft 495 50 and has pivotally connected thereto an actuating rod 499 (Figs. 23 and 7), the lower end of the actuating rod being pivoted at 500 to a front end of a lever 501 which is pivoted at 502 to a base portion of the machine 55 frame. The other end of the lever 501 carries a roller 503 which is adapted to rest on the periphery of the master cam and also (Fig. 7^b) to ride on the peripherally-projecting cam 504 carried by the master cam. 60 By this construction the cutting disk 482 is oscillated into and out of its cutting position with reference to the spreader, as indicated in Figs. 23 and 24. These two side-slitting devices are for the purpose of forming arm- 65 holes, side slits in drawers, and other opera-

tions confined to one or both edges of tubular goods when stretched flatwise on an anterior spreader; and the devices are particularly useful in connection with the manufacture of union suits, shirts and 70 drawers.

A coil spring 505 attached at one end to the machine frame has its other end attached to the rod 499, the tension of the spring being exerted to force the rod 499 down and thereby 75 exert a pressure on the lever 501 and keep the roller 503 in working contact with the master cam and the cam 504. Cam 504 constitutes the side-slitter cam.

Cutting union suits.—In Fig. 32 I show 80 a layout of distended tubular goods, omitting the spreader for clearness. In this figure x represents the bottom and x' the top 85 walls of distended tubular goods as the goods pass through the machine. The spreader used to flatten the goods is omitted for clearness. The wall x forms the front of the garment and the wall x' forms the back of the garment. Assuming that this piece of tubular goods generally indicated 90 by 506 is being fed through the machine in the direction of the arrow shown in Fig. 32, then 507 represents the neck portion of the garment at the shoulders and 508 the arm-hole slits. The slit indicated by 509 is the 95 front opening, while the cut-out 510 represents the ends of a gusset opening, and the intermediate hole or opening 511 represents a space from which material that I herein 100 call the crotch-piece is removed. 512 indicates the cross cut-off at the ankles when two garments are separated from one piece of tubular goods.

The side-slitting knives 482 form the arm-hole slits 508. The hooked knife 435 (Fig. 105 35) operates underneath the work while the arm-hole slits are being cut and is indicated by A' in Fig. 31, and while the neck portion 507 is being fed over and out of contact with the upper end of the knife. The knife then 110 rises up and cuts into the bottom wall x of the flattened tube, the upper and under walls of which are at this point held in contact as the goods pass under the foot 253 (Figs. 73 and 74). This operation is indicated by B' 115 in Figs. 31 and 34, and the knife operates in its path B' from the neck portion at x² (Fig. 32) to x³. At this point, from x² to x³, only one of the jig-knives is in cutting 120 operation; but at x⁴ the sewing machine carrying the jig-knife which has just been operating to form the front opening 509 is shifted slightly and this slight shifting movement is indicated by the bent line x⁴. Simultaneously with the lateral shifting 125 movement, the same jig-knife that has been operating cuts along the line x⁵ to the apex of the approximately oval shaped hole 511; but in this latter movement the jig-knife in cutting operation is projected upwardly to 130

move in the path C', the point of the jig-knife penetrating both the walls x and x' in its cutting action along line x^5 . Simultaneously with the commencement of the cutting action of the aforesaid jig-knife along line x^5 the second jig-knife carried by the other sewing-machine head begins to cut practically at x^3 , and cuts along the line x^6 parallel with the line x^5 until it reaches the apex of the hole 511. For accuracy of statement it may be here mentioned that said other jig-knife never moves in the path B' but moves from the inactive path A' to the path C' which involves a movement through both walls of the goods. The reason is that only one jig-knife is necessary to form the front-opening slit 509. When the forward apex of the hole 511 is reached the two sewing-machines begin to stitch each a seam x^7 , each of which is an inside seam of a garment leg; and at this time the machines travel apart each carrying its own jig-knife and each jig-knife then operating adjacently a seam x^8 and so cutting at the two opposite sides of the hole 511. After the goods have traveled past the ankle cut-off 512 the ankle cut-off takes place, the crotch-piece 513 having first been detached at its front end and fed downwardly as hereinafter described. In the feeding movement of the goods the sewing machines finally converge at the forward apical portion of the hole 511, the sewing operation stops and one jig-knife cuts along the line x^9 while the other jig-knife cuts along the parallel line x^8 , but when the jig-knife cutting along x^9 reaches the point x^{10} it drops into its non-cutting position A' while by a shifting movement of the other sewing-machine head, which shifting movement is indicated by x^{11} , that jig-knife falls from the path C' into the path B' and cuts along a successive front opening 509 until it reaches a second neck-opening space 507. This mode of operation is continuous throughout the length of the bolt of tubular goods under conversion into union suits cut to shape, length and size, and two union suits are successively formed from a portion of the bolt, the ankle ends of the legs of two suits being primarily adjacent but being transversely severed at the cut-off 512. The same is true of the shoulder-portions of two adjacent garments, which are severed at the transverse cut-off x^{12} . A coil spring 525^a has one of its ends connected to the machine frame and its other end connected to the rod 525, the tension of the spring pulling this rod downwardly, exerting a spring pressure on the lever 526 and keeping the roller 527 in working contact with the periphery of the master cam and the peripheral cam 528 which constitutes the crotch-piece-deflector cam.

The main feed-rolls and crotch-piece feed-

rolls.—The crotch-piece 513 is cut from the hole 511. The end portions 514 of the crotch-piece are respectively cut from the spaces 515 at the opposite ends of the opening 511. The goods are fed through the machine by the main feed-rollers 516 (Figs. 7, 16, 23, 28, 29 and 30). These main feed-rollers are mounted in brackets 517, and driven as stated in my patent No. 1,114,082 of October 20, 1914. The brackets support a transverse-horizontal rod 518. Each end 75 of the rod is provided with an up-standing fixed arm 519, and an upper transverse horizontal rod 520 runs from one to the other arm 519. Toward one end of the feed-rollers the two rods 518 and 520 thereabove support a plate 521 (Figs. 7 and 16) to which is pivotally secured at 522 a lever 523, the outward end of which has pivotally connected thereto at 524 a downwardly-extending lever-actuating rod 525 (Fig. 7), 85 the lower end of which is pivotally connected to the outer end of a lever 526 which is pivotally mounted at 502 on the base portion of the machine, the inward end of the lever 526 (Figs. 7^b and 8) carrying a roller 90 527 which works on the peripheral surface of the master cam and also rides over the peripherally-projecting cam 528. From this cam 528 movement is given to the lever 523 for actuation of the vertically reciprocable 95 crotch-piece deflector 529 which is connected to the inward end of the lever 523 at 530. This slidable deflector 529 has its edges mounted in vertical ways in a guide-block 531 mounted on the rods 518 and 520. The 100 crotch-piece deflector 529 has near its lower end a forwardly-projecting integral yoke 532 projecting downwardly and carrying a transverse horizontal feed-roller 533 above and co-operating with an under feed-roller 105 534 which is conveniently made of the same length as the main feed-rollers in order to be received in the side walls of the machine. These two feed rollers 533 and 534 constitute the crotch-piece feed rolls. The under 110 end of the crotch-piece deflector is offset at 535 (Figs. 28, 30) and extends downwardly back of the feed roll 533 to about the level of the upper periphery of the under feed-roll 534 when the deflector is in its highest 115 position, being then slightly clear of the surface of the goods 506, the goods then being nipped by the main feed-rollers 516 and passing under but out of contact with the upper crotch-piece feed-roll 533 and 120 the crotch-piece deflector 535, and above the under crotch-piece feed-roll 534, as shown in Fig. 28.

The under main feed-roller 516 has one end of its shaft provided with a gear 536 125 (Fig. 22) which meshes with an intermediate gear 537 journaled to the frame side and in turn meshing with a gear 538 fast on an

end of the shaft of the under crotch-piece feed-roller 534. The intermediate gear 537 is used because there is a space between the main feed-rolls 516 and the crotch-piece feed-rolls 533 and 534 down into which the crotch-piece when severed at its advancing end is deflected by a downward movement of the deflector 535. A convenient way of mounting the under crotch-piece feed-roller 10 534 is by providing pivot-pins 540 in the main frame, the inward ends of the pivot-pins centering in the ends of the journal of the feed-roll 534 as shown in Fig. 16. A plate 541 is mounted in front of the under 15 crotch-piece feed-roll 534 for a portion of its length about midway between the sides of the machine, and is secured to a transverse rail 492 secured to the main frame of the machine. The under margin 542 of this 20 plate 541 passes rearwardly of the rocker shaft 495. The purpose of the plate and its arrangement in this location is to prevent the crotch-piece, after its advancing end is severed and as its sides are progressively 25 formed, from getting in under the feed-roll 534 or becoming entangled with the bar 492 or the rocker shaft 495.

Crotch-piece cutting and delivering mechanism, (Figs. 28-33.—The crotch-pieces re-30 moved from the goods in the manufacture of union suits or drawers, are dropped into a receptacle under the machine. Secured to the side brackets 517 is a transverse plate 543, concave on its rear side to fit closely 35 up to the bottom main feed-roller 516. Secured to the plate 543 is a plate 544 (Figs. 21 and 23). The upper edge of the plate 544 is transversely bored at 545 throughout its length to form a bearing for the endwise-40 reciprocating knife-carrying rod 546. The upper edge of the plate 544 is made with a lengthwise-extending slot 547 to receive the body 548 of the upwardly-projecting transversely-extending toothed cutter 549. The 45 walls of the slot 547 are toothed to form stationary cutting teeth 550 at each side of the teeth of the toothed cutter 549. There are two series of stationary teeth 550, one tooth being back of another, and the teeth of the 50 toothed cutter 549 reciprocate endwise between the two series of stationary teeth very much as in the mowing-machine cutter. The rod 546 extends from one end of the toothed cutter 549 toward the side of the machine 55 (Fig. 16) and its outer end is socketed in a hole drilled in the end of the T-slide 551, the rod end being clamped in the bore by a clamp screw 551^a (Figs. 19, 20). The slide 551 reciprocates in a T-slot 552 of a bracket 60 553 which is secured to the machine frame at 554 (Fig. 16). A pitman 555 is pivotally connected to the T-slide 551 at 556 and is operated by an adjustable crank 557 carried in the diametric slot of a disk 558 (in a

well-known manner) which is mounted on 65 a shaft 559, the inner end of which is provided with a bevel-gear 560 which meshes with a bevel-gear 561 on a rotary shaft 562. The gears 560 and 561 are inclosed in a housing 563 which is supported in a yoke 70 564 supported by a standard 564^a carried by the machine frame 383. The shaft 562 is mounted horizontally, the housing having a lateral extension 563^a which is gripped in the yoke 564 and which is bored to form 75 one bearing of the shaft 562. Another yoke 565 spaced apart from the yoke 564 is supported by the standard 564^b rising from the machine frame 383. A bearing 566 for this end of the shaft 562 is held in the yoke 565, 80 and the shaft is provided with thrust-collars 567, 567 at each end of the bearing 566 to prevent its receiving endwise movement. The shaft 562 is provided with a driving pulley 568 operated from a belt 569 that 85 is driven from a belt-wheel 570 fixed on the main shaft 4, and the shaft 562 is provided with a universal joint 571 one member of which carries the operating shaft 571 of the auxiliary feeder referred to in my said 90 patent and in this case generally indicated by 572 in Fig. 7.

From the foregoing it will be seen that as the shaft 562 is rotated, the gears 561 and 560 give movement to the crank 557 for reciprocating the pitman 555 endwise, thereby drawing the slide 551 endwise and giving a reciprocating lengthwise action to the tooth cutter 549.

The combined cutting teeth 549 and 550 100 are located so that the teeth 549 are just below the path of the travel of the fed goods (Fig. 28) and as the advancing goods reach the end of the first cut-out 510 (Fig. 32) in cutting union suits, the peripherally-projecting cam 528 on the master cam (Fig. 7^b) contacts with the roller 527 actuating the lever 526, the rod 525, and moving the lever 523 and the crotch-piece deflector 529 so as to cause the end 535 of the latter to 110 press the advancing crotch-piece end 514 downwardly as shown in Fig. 29 against the associated teeth 549 and 550, and thereby transversely sever the advancing end 514 of the crotch-piece which then falls into the vertical position shown by dotted lines in Fig. 29. As the goods 506 continues in its feeding movement rearward, the fallen end 514 hangs down toward a receptacle or the floor, and when the rearward crotch-piece end 120 514 reaches the stage for its transverse separation from the goods, the hanging crotch-piece is carried under the deflector end 535 and into spaces between the associated cutting teeth 549 and 550, and as the toothed cutter 549 is reciprocating endwise the rear end 514 is cut from the goods and the freed crotch-piece falls. The toothed cutter 549

is reciprocating continuously. At this second transversely-cutting movement for releasing the crotch-piece, the roller 527 falls from the peripheral cam 528 and the crotch-piece deflector is lifted.

The lubricating system. (Figs. 5 and 84-89.)—The reservoir 194 is supplied with oil through an opening 573 of the sewing-machine trunk, each sewing machine being provided with one of my new lubricating systems. The drip-pan 193 at the upper end of the reservoir is provided with a depressed perforated portion forming the oil-strainer 574. From the drip-pan the oil gravitates into a compartment 575 at the outer side of the reservoir which is interiorly provided with parallel vertical walls 576 which are spaced apart to carry a body of oil-filtering material 578 in the space between them. The walls 576 are frequently perforated at 577 and the oil flows from the compartment 575 in the direction indicated by the arrows and into the reservoir compartment 579 forwardly of the walls 576. In compartment 579 the oil pump 195 has its induction tube 580 extending downward toward the bottom of the reservoir compartment 579. The pump induction tube 147 extends upwardly from the pump into the chamber of the trunk 171 of the sewing machine to conduct the pumped oil to the oil conduit 148.

The pump comprises two small thin spur-gears 581, one of the gears being provided with trunnions 582 journaled in the side walls of the pump casing, and the other gear being fixed on a shaft 583 which is journaled in the side walls of the pump casing and has one of its ends extended to receive the pump-driving pulley 196. The pump casing 195 comprises a recessed block and a cover therefor, the block having an elongated recess 584 of a depth of the thickness of the two gears 581 which are of the same thickness and of a length sufficient to receive the two gears when intermeshed (Fig. 88). The block is provided with alined holes one at its under and the other at its upper side for reception respectively of the pump induction and ejection pipe which are alined with the intermeshing peripheral portions of the two gears. The outward face of the block has an annular recess 585 the bottom of which is flush with the outward surfaces of the intermeshing gears, and the outward face of the block has another annular recess 586 concentric with the recess 585, but of larger diameter than the recess 585, and this recess is inclosed by the margins 587 of the outward face of the block which is indicated by 195. The cover is formed of a disk having on its inner face an annular projecting boss 588 of a diameter to fit into the recess 585 with the inward face of the boss close up to the outward faces of the intermeshing

gears. This cover is also provided with an annular flange 589 which fits into the recess 586 and is forced air-tightly thereinto. The boss is provided on its inner face with bearing holes 590 which extend only part way through the boss and support one an end of the gear shaft 583 and the other a trunnion of the gear 582. The purpose of making these bearings as blind holes is to insure air-tightness of the pump. The pump-gears 581 and 582 as shown are full size, and so also is the entire pump structure illustrated. It has been found in practice that a pint of oil can be passed through each sewing machine every three minutes by means of this pump, which is practically efficient in keeping some oil-containing parts constantly filled with oil, and other oil-containing parts continuously lubricated by oil spray produced by either the centrifugal or vibrating forces of the high-speed parts. The top shaft 83 is bored throughout its length to form an oil conduit 590, the outward end of the top shaft projecting into the oil chamber 146 (Fig. 84). The front end of the oil conduit 590 is plugged at 591, and the reduced portion 85 of the top shaft has its wall drilled at 592 to form oil conduits leading from the oil conduit 590 in the top shaft and permit the passage of oil from the conduit 590 to the front top-shaft bearing 84. The top-shaft-inclosing tube 82 projects forwardly beyond the front wall of the bearing 84 forming a housing 593 for the needle-driving crank. The ball crank members of the top shaft are drilled at 101^a to form oil conduits from the conduit 590 of the top shaft to the bearings for the ball cranks, and surplus oil flows therefrom down the connecting rods 164 to the respective ball-bearings 168 and 180 thereof. The wall of the rear portion of conduit 590 in shaft 83 is drilled at 83^a, and the inclosing forward end of the ball-bearing section of the top shaft is coincidentally drilled at 83^a to form conduits from the conduit 590 to the rearward bearing 84 of the top shaft. The wall of the conduit 590 is perforated at 590^a within the housing to form an oil conduit from the conduit 590 into an oil conduit 590^b formed by drilling the needle-driving crank 87. This conduit 590^b discharges on the front advancing surface of the crank 87 (Fig. 63) at one side of the crank-pin 88 and the oil flows down the advancing surface of the rotating crank to and lubricates the crank-pin 88 in its bearing in the upper end of the needle-driving link 89. Some of the oil flowing out on the crank and going to the crank-pin bearing is whirled off by centrifugal force and is caught within the housing 593; and other of the oil coming to the crank-pin bearing flows down the crank-pin to and lubricates the connection at 90 of the

needle link 89 with the needle-holder 91, and this oil escaping at the connection 90 finds its way to the needle-holder guide-bar 93 and to the needle-holder ears 94 that reciprocate in the groove 95 of the needle-holder guide 98. It will be observed that the oil passing through the conduit 590^b is forced thereinto by centrifugal force and it is found in practice that the amount of oil finally coming to the needle-holder and needle-holder guide is, while sufficient for lubrication purposes, negligible so far as any deposit of oil on the goods is concerned. In connection with the lubricating system and the needle-holder guide 98 (Fig. 67) the shank of the latter is formed with an oil conduit 98^a which extends downwardly to near the bottom of the needle-holder guide-bar 93, the chamber 98^a having its wall perforated as at 98^b for escape of oil to the outer surface of the needle-holder guide-bar. The top-shaft-inclosing tube at its front end and lower portion has a transverse web 594 which forms a dam to hold back in the housing any oil that may drop in the bottom thereof. The bearing 84 on its under side has a lengthwise bore forming an oil conduit 595 that leads rearwardly in the bottom of the tubing 82 any oil from the under side of the housing 593, and such oil flows back through the conduit 595 flows along the bottom of the tube 82 to the oil conduit 596 formed in the bottom of the rearward bearing 84 for the top shaft. The rear end of the conduit 596 discharges within the housing or cap 155 and falls down on the incurving under sides of the cap 155, and runs along the inner margins of the cap adjacent the edges 158 thereof to the point 159, and drips therefrom into the oil-receiving V-space 599 in the upper side of the bell-crank 167 (Figs. 5 and 84) oiling the journal of the bell-crank. The oil which lubricates this journal flows down the lower bell-crank arm to its end 169 within the tube 170 and flows toward the front end of the machine through the conduits 176 in the plug 175, and thence flows forwardly within the tube 171 until it reaches the block 172 which is provided with oil conduits 172^a through which the oil flows into the forwardly-extending portion of the tube 171, escaping therefrom through the bores 600 in the wall of the tube 171, these bores forming oil conduits for lubricating the front end of the tube 171 in the front and rear bearings 181. As the shaft 171 reciprocates, some of the oil between the front end of the tube 171 and the bearing 181 escapes into the annular recess 184 formed in the front end of the block 172 around the projecting end of the tube 171, and from this recess the oil flows into the rear-going conduit 183^a formed through the bearing 181 under the front end of the tube 171. The oil thence escapes into the 65 chamber of the looper-shaft casing 182, and flowing rearwardly therethrough, flows into the conduit 183 formed through the rear bearing 181 for the hollow looper-shaft 171. This conduit 183 discharges the returning 70 oil into the drip-pan at the top of the oil reservoir. The oil chamber 146 is provided with an oil outlet 601 (Fig. 5) from which a conduit 602 leads into a position above the oil-receptacle 215 of the stop-motion for the 75 top shaft. This oil falls into the filtering material 216 and flows thence, as already described, to the shock-absorbing plug in the front end of the stop-motion lever 214. The chamber 146 is kept filled with oil by 80 the pump and oil leads therefrom not only between bearing surfaces already described, but very markedly through the recurrent vacant portion of the keyway 119 so that all the moving surfaces of the top-shaft stop-motion are continuously lubricated with 85 filtered lubricant forced into place by the pump, the surplus oil returning by gravity to the oil reservoir.

Incasement of operating parts of the sewing machines, and other advantages.—As already stated, the rearward operating parts of the top-shaft and looper-shaft together with other parts already described are wholly incased by the sewing-machine 90 trunk. Such incasement is a novel feature 95 of my invention. The very great speed of each of the two sewing machines is of such practical importance that I have devoted much time and expense especially to the 100 stop-motions for the top shafts and to the lubricating system, with the result that these two features of the invention are of prime importance in the combined cutting-and-stitching machine.

The main-shaft clutch-mechanism comprises the following advantages: The spring pull-out stops the entire machine gently without shock. Starting and stopping manually does not disturb the latched position of 105 the swing-bracket 17, this bracket unlatching only on the breakage of the needle thread. The manual starting and stopping movements of the main-shaft clutch when it is operated by the movement of the trolley 115 rails is independent of the swing-bracket 17 after it has once been brought to its latched position and while the thread is in the needle ready for or during a sewing operation. On the breakage of the needle thread the electric switch is closed, energizing the magnet B which lifts the latch tooth 24 away from the slide-bar 16 so that it drops on the rim of the fly-wheel. As the cam 15, carried by the fly-wheel, lifts said slide, the latch 20 120 engages the bottom edge of the latch 39 to disengage the tooth 40 from the extension 36, at which time the bracket 17 is moved

outward by the pull of the spring 34. Thus the bracket 17, which is in contact with the lever 30 secured to the starting-post 9 and which overlaps the bracket 17, is moved, 5 turning the starting-post in its bearings and shifting the trolley rails, and also shifting the spool clutch member 7 away from the clutch arm 6, thereby stopping the entire machine simultaneously with the unlatching 10 of the swinging bracket 17. The slide 16 is raised so that the tooth 24 reengages the notch 23, holding the slide in its raised position.

The thread-controlling mechanism comprises the following advantages. While a sewing machine is stitching, the needle thread is clamped each time the needle rises, by the nipper spring 276 carried by the link 89, the clamping being effected between the 15 spring and the thread tube 281, or between the spring and the swinging plate 271, and such clamping of the needle thread assists in forming a loop thereof for the looper to enter. The nipper spring remains closed on 20 the needle thread while the needle is in its highest position or stopped, in order to prevent the needle thread from being pulled back from the needle.

The thread-measuring mechanism comprises the following advantages. It measures off sufficient thread at the end of each stitching operation, and insures a positive stitching when the needles and looper are in coöperation. It prevents the breakage of the 25 needle thread so that the needle will not become unthreaded. It prevents the action of the trip-rod which controls the electric switch of the main-shaft clutch from stopping the machine when the thread is broken intentionally. It provides a loose needle-thread when the machine is started, to assist 30 in forming the first few stitches. It pulls the thread out of the tension, thereby overcoming the drag of the tension in such a way 35 that the thread passes through the needle eye easily prior to the thread being broken close to the work.

The looper-thread-breaking mechanism comprises the following advantages. It 40 draws out the looper thread after each stitching operation to insure positive stitching when the machine is again started. It grips the looper thread against the pull of the work, to break the looper thread close to 45 the work. It returns to its initial position before the machine starts sewing and releases the looper thread end, so that the looper thread is drawn up in the work, when the sewing begins. It is positive in its operation 50 because the looper thread is always in the needle hole of the breaker slide when the machine is sewing, and therefore the looper thread is broken accurately each time a stitching operation is interrupted automatically. On the other hand, should the entire

machine be stopped automatically at any time for any reason, such starting and stopping does not effect actuation of the looper-thread-controlling devices. This is a very important feature of the invention because 55 if during the operation of the entire machine, the material which the machine is operating upon should be defective so as to necessitate stopping the machine, or if for any reason the machine should be stopped 60 during a normal stitching operation of a given article, the manual stopping of the machine should be so arranged as not to break or otherwise disturb the looper or needle threads, which would cause defective 65 stitching at the stopping point. It is for this reason that the thread controlling and breaking mechanisms are actuated independently of the automatic starting and stopping means provided for the sewing machines. 70

The top-shaft stop-motion comprises the following advantages. The parts are made as light and small as possible and of the strongest material possible, and are balanced to overcome vibration. The depth of 75 the stop-tooth 117 is preferably not more than one-eighth of an inch, and this permits a corresponding short movement of the stop-finger 239, thus involving a very short 80 range of movement for the trolley rails, overcoming loss of power and obtaining quick action. The stop-motion actuating-cams 62, 62 carried by the master cam are low peripheral projections from the periphery of the master cam, the step from one 85 lift to the other being preferably about one-eighth of an inch, thereby enabling the roller 60 to mount the steps easily. The trolley rails actuated by the stop-motion actuating-cams 62 are arranged so as to have 90 a positive movement upwardly and a combined spring-and-gravity movement downward, thus effecting a saving in power required for moving the trolley rails. While 95 the rollers 60 serve the purpose of actuating the needle and looper thread controlling and breaking mechanism in the coaction of the rollers with the steps 63 of the cams 62, the coaction of the rollers therewith 100 does not affect any movement of the trolley 105 rails. And the coaction of the rollers 60 with the steps 64 of the cams 62, controlling the actuation of the top-shaft stop-mechanisms through the trolley rails does not 110 affect the action of either the needle or looper thread-controlling mechanisms, although all the mechanisms in question are 115 interconnected. Such interconnection is accomplished in a manner that permits their 120 respective movements to be independent at 125 certain times and when required. This is important because if such movements were not relatively independent, the looper-thread-breaking slides would be actuated simultaneously with the stopping and start- 130

ing of the sewing machines with the result that the needles would be broken each time the sewing machines were stopped.

The lifting movements of the trolley 5 rails exerted on the top-shaft stop-motion levers is such as instantly to release the pressure of the brake-shoes 130, and the time of such releasing action may be regulated by the screws 209, while the pressure 10 on the brake-shoes may be regulated by the pressure of the screws 142 on the springs which surround the pressure plugs 139 operating on the brake-shoes respectively. In 15 starting the sewing machines the pressure plugs 139 are lifted from the brake-shoes 130. This lifting action of the brake-shoes permits the springs 124 to rock the sleeves 108 and thereby effect the clutching action of the balls 111. As this clutching action 20 occurs, the stop-fingers 239 are withdrawn out of the paths of the stop-teeth 117, permitting rotation of the top shafts. On stopping the top shafts the pressure plugs are first permitted to engage with the brake- 25 shoes, the brake-shoes then pressing upon the portions 116 of the sleeves 108 and overcoming the counteracting tendencies of the springs 124, and thus releasing the balls 111 from their clutching positions; and at 30 this time the stop-fingers 239 are returned into the paths of the stop-teeth 117 so that they arrest the rotation of the sleeves 108, turning the segmental keys 120 into the abutting positions indicated in Fig. 40 and 35 thereby stopping the rotation of the top shafts which are connected with the sleeves by the segmental keys 120. When the segmental key comes into the abutting position shown in Fig. 40, it forces out the 40 lubricant which is in advance of the keys during the rotation of the top shafts. The engagement of the clutch-balls with the clutch-wheels being controlled by the action of the very delicate springs 124, the 45 movement of the brake-shoes is required to be merely sufficient to overcome the tension of the springs in order to release the balls prior to the stopping of the top shafts. The lubrication arrangements of the stop- 50 motions effect the action thereof without appreciable shock and without noise in spite of the high speed of the moving parts. The arrangement of the top-shaft stop-motions and drive-belts therefor entirely with- 55 in the trunk, permits the convenient flooding of the stop-motions with oil without liability of its getting outside of the sewing machines and flying off into space.

The stitch-forming mechanism comprises 60 the following advantages: The needle drive is simple. The weight of the usual needle-bar is entirely eliminated, the needle-driving link taking the place of the usual needle-bar and a needle-link in prior ma- 65 chines, and my needle-driving link and

needle-holder not necessarily being heavier than the ordinary needle-chuck used with ordinary needle-bars. This reduction of weight is very material in overcoming vibration, noise, and general wear and tear at 70 high speed. The needle-holder guide-bar supports and guides the needle close to the work, thereby overcoming much friction heretofore encountered, and permitting these parts to be lubricated by the gravity- 75 lubricating system heretofore described, in consequence of the bearings or wearing surfaces being below the top shaft from which the oil gravitates. The needle-drive is a direct thrust. The thrust from the link 80 is directly over the needle shank, and very powerful action is obtained with very light construction which is favorable to the high speed in question. The top and bottom shafts of the sewing machines are tubular, 85 diminishing weight and giving strength to the shafts. Their incasement in tubes keeps the bearings of shafts in proper alignment. The construction enables the shafts to be assembled in tubes outside of the sewing machine frames, thus facilitating the substitution of one mechanism for another 90 for the purpose of repairs or otherwise.

The jig-knife construction comprises the following advantages. It permits the ma- 95 chine to effect design cutting either during a stitching operation or independently thereof, and also permits the machine to effect interrupted cutting without stopping the feed of the goods by the use of a jig- 100 knife carried by a sewing-machine head from which the band cutter has been removed. The band-knife arrangement is not available for doing interrupted cutting in continuous high-speed operation of the ma- 105 chine. The jig-knife may be automatically projected up into the goods so as to cut one thickness along certain lines, and be projected further to cut two thicknesses at other places, and may also be moved out 110 of the path of the goods. The jig-knife is so arranged as to be readily attached or detached, and provision is made for the quick removal of the band-knives. Consequently the machines may be interchange- 115 ably equipped with either form of cutter conveniently and as desired. The means for controlling the cutting action of the jig- knives being carried by the master cam, enables the master cam to be assembled with 120 said means prior to the location of the master cam in the machine and while the ma- chine is doing some other kind of work. Thus time is saved.

The side-slitters comprise the following 125 advantages. Small electric motors mounted so as to swing to and from the goods operate the circular knives at high speeds which insures a long cutting life to the knife edges, and reduces the necessity of resharpen- 130

ening such edges to a minimum. The motors are adjustable to and from one another to accommodate different widths of goods, and may be readily removed or attached.

5 The crotch-piece cutting and severing mechanism enables the cutting out of the crotch-pieces in advance of the main feed-rolls, and also in advance of the length-cutting mechanism. This results in not cutting up the crotch-pieces of two contiguous garments into smaller pieces, but yields large-size crotch-pieces which are available for good-size gussets and other purposes.

15 The lever 359 and cone collar 361 of the thread-measuring mechanism constitute a catch referred to in the claims.

The hereinbefore - described mechanisms have been invented with particular reference to meeting the high-speed conditions of my combined cutting-and-sewing machine. Various features of the hereinbefore described invention are set forth in my following divisional applications filed January 25 2, 1919.—Serial No. 269,273, needle-actuating and control and work-holding foot mechanisms; Serial No. 269,275, cutting attachment for cutting machines; Serial No. 269,276, sewing machine; Serial No. 269,277, thread-breaking mechanism; and Serial No. 269,279, over - stitch mechanism; the described lubricating system is set forth in my divisional application Serial No. 94,354, and the stop motion in Serial No. 94,355, both filed April 29, 1916; and the described thread-controlled electric stop-motion is set forth in my application Serial No. 269,478, filed January 3, 1919. For example, the hollow shafts of the sewing-machine heads are of peculiar importance in my high-speed combined cutting-and-sewing machine because their weight is reduced in consequence of their being made hollow, and this reduction of weight reduces the centrifugal force, tending to impair the efficiency and to break the stop-motions for the drive-shaft of the sewing machine. And the lubricating system is also of peculiar utility in these high-speed machines because of the necessity of automatically and liberally supplying the sewing-machine parts with oil during their travel in high-speed operation. The different forms of thread-concatenating devices have been devised with especial reference to their availability in a machine of this kind, even the work-foot being of a new construction and not an ordinary presser foot of known type because of the practical requirement that it yield to meet variations in thickness of the piece of goods being drawn rearwardly through the machine by the feed-rollers, the sewing-machine heads themselves being characterized by the absence of contained work-feeding means.

The thread-breakers effect a substantial saving of thread, obviate manual trimming, improve the neatness of the finished work, and prevent long thread ends from catching and winding around parts of the machine. 70

What I claim is:

1. The combination in a machine having a pattern-cam control, of a main shaft; a fly and driving wheel loose on the shaft, the wheel having a laterally - projecting rim; a spider fixed on the shaft and located within said rim, the spider being provided with spring plates for engaging said rim; clutch - levers pivotally mounted on the spider and constructed to engage the spring- plates; a slidable member on the shaft constructed to engage and disengage the levers; means for moving said member, such means comprising a rockable starting-post; trolley rails and link connections operatively connected with the starting post; a cam mechanism for raising and lowering the trolley rails; operative connections between the latter and the trolley rails; an implement-carrying head; a pattern cam; operative connections between the pattern cam and the implement-carrying head, for moving the latter; and a stop mechanism under the control of the trolley rail and constructed and operating to arrest the operation of 90 the implement carried by said head.

2. The combination in a machine having a pattern-cam control, of a main shaft; a fly and driving wheel loose on the shaft, the wheel having a laterally-projecting rim; a spider fixed on the shaft and located within said rim, the spider being provided with spring plates for engaging said rim; clutch-levers pivotally mounted on the spider and constructed to engage the spring-plates; a 100 slidable member on the shaft constructed to engage and disengage the levers; and means for moving said member, such means comprising a rockable starting-post; said wheel carrying a cam; a swinging bracket on the starting-post and carrying a slide an end of which may come in the path of the cam; a latch carried by the slide; a lever pivoted to the swinging bracket and having an arm with which the slide is constructed to engage; and an electric contact with which the lever may be contacted; a movable sewing machine; means for effecting its travel during its operation; means for arresting its operation; means for arresting its travel; and an electrically operated signal connecting with said electric contact. 110

3. The combination in a machine having a pattern-cam control, of a rockable starting-post; a fixed rocker arm thereon; a main shaft provided with a movable clutch-member; means operatively connecting said clutch-member with the starting-post; a loose fly-belt-wheel on the main shaft; a 125 130

clutch mechanism fixed on the main shaft and operable by said clutch-member; and loose on the starting-post an armature-carrying bracket; a magnet energizable on the 5 breaking of a thread of the sewing machine; said sewing machine; mechanism for latching the bracket against the tension of a spring; said spring; means comprising the armature for unlatching the bracket on the 10 breakage of the thread; and means for thereupon energizing the magnet; mechanism for moving the sewing machine during its sewing operation; a trolley rail; means for reciprocating it; a stop motion operatively connected with the trolley rail and the sewing machine; and a signal operatively connected with the magnet.

4. The combination in a machine having a pattern-cam control, of a rockable starting-post; a fixed rocker arm thereon; a main shaft provided with a movable clutch-member; means operatively connecting said clutch-member with the starting-post; a loose fly-belt-wheel on the main shaft; a 25 clutch mechanism fixed on the main shaft and operable by said clutch-member; and loose on the starting-post an armature-carrying bracket; a magnet energizable on the breaking of a thread of the sewing machine; said sewing machine; mechanism for latching the bracket against the tension of a spring; said spring; means comprising the armature for unlatching the bracket on the 30 breakage of the thread; and means for thereupon energizing the magnet; a trolley rail operatively connected with the starting-post; a stop-motion for the driving shaft of the sewing machine operatively connected with the trolley rail; and means for 35 lifting the trolley rail positively; a pattern cam; and connections between the pattern cam and the sewing machine for moving the sewing machine during its sewing operation.

45 5. The combination in a machine having a pattern-cam control, of a pattern cam; a movable sewing machine; a track therefor; operative connections between the pattern cam and the sewing machine to effect travel 50 of the latter on its track; a raisable and lowerable trolley track; a stop-motion for the drive-shaft of the sewing machine; a starting lever for the stop-motion, such starting lever working on the trolley track; 55 and means for lifting the trolley track positively.

6. The combination in a machine having a pattern-cam control, of a sewing machine; a stop-motion for its driven shaft; a raisable and lowerable trolley rail; a stop-motion-actuating lever working on the trolley rail; and positive means for lifting the trolley rail positively; a pattern cam; a track for the sewing machine; connections 65 between the pattern cam and the sewing

machine for moving the sewing machine on its track; and other means for driving the sewing machine.

7. The combination in a machine having a pattern-cam control, of a movable sewing machine; a track therefor; a pattern cam; operative connections between the sewing machine and the pattern cam to effect travel of the sewing machine on its track; a thread-measuring mechanism; a thread-breaking mechanism; a cam moving with the pattern cam; and operative connections between the cam moving with the pattern cam and the thread measuring and breaking mechanisms for operating the latter. 80

8. The combination in a machine having a pattern-cam control, of a sewing machine; a track therefor; means for moving the sewing machine on its track, while its stitch-forming instrumentalities are in operation; 85 a needle-thread-measuring apparatus carried by the sewing machine and comprising a trip-lever having a thread eye in its free end, and a measuring lever having a thread eye in its free end. 90

9. The combination in a machine having a pattern-cam control, of a sewing machine; a track therefor; and means for moving the sewing machine on its track; with a thread-breaking mechanism; a slide; means connecting the slide to the thread-breaking mechanism; and a track for the slide, the slide being carried by the sewing machine. 95

10. The combination in a machine having a pattern-cam control, of a sewing machine comprising a hollow upper arm; a troughed member extending lengthwise of the chamber of said arm; a hollow under arm; a troughed member extending lengthwise of the under arm; a top shaft and bearings therefor within the upper troughed member; an under shaft and bearings therefor within the under troughed member; operative connections between the two shafts; a device actuated by the under shaft in the formation of stitches; a needle-actuating crank fixed on the top shaft; a needle-driving link actuated by the crank; a needle-holder pivoted to the link; and a guide-bar for the needle-holder; all in combination 100 with a track on which the sewing machine is movable; and means for moving the machine on its track while its stitch-forming devices are in operation; and a work foot constructed and operating to glide over the goods and to yield to variations of thickness of the goods sufficiently to permit said gliding movement during the travel of the machine. 115

11. The combination in a machine having a pattern-cam control, of a sewing-machine head; a shaft therein; a needle-actuating crank carried by the shaft; a needle-driving link pivoted to the crank; a needle-holder pivoted to the link; and a guide-bar for the needle-holder fixed to and carried by the 120 130

- head; the needle-holder being held by the guide-bar in a fixed path of vertical reciprocation; a track for the sewing machine; and means for moving it on the track; and a work foot constructed and operating to glide over the goods and to yield to variations of thickness of the goods sufficiently to permit said gliding movement during the travel of the machine.
12. The combination in a machine having a pattern-cam control, of an arm of a sewing machine; a needle-drive shaft carried by the arm; a needle-actuating crank fixed on the shaft; a needle-actuating link pivoted on the crank; a needle-holder pivoted on the link; a vertical needle-holder guide-bar fixed on the arm; the guide-bar holding the needle-holder in a path of vertical reciprocation; a looper made with two laterally projecting jaws one above the other, the upper one being furnished with a hook and the under one with an eye, both jaws being above the free point of the looper; and means operatively connecting the looper for actuating it with said crank; a work-foot; and a throat-plate; said connecting means operating to reciprocate the looper and its point; a track for the sewing machine; and means for moving it on the track; said work foot being automatically adjustable to suit variations in the thickness of the goods, and being constructed and operating to glide over the goods during the travel of the machine.
13. The combination in a machine having a pattern-cam control, of a throat-plate having a hole for passage of a needle with an adjacent slit and a therefrom dependent guide, the slit and guide permitting the passage of one run of a band-knife; a band-knife; band-knife supports; and means for driving the band-knife; a sewing machine carrying the band-knife; a track for the sewing machine; and means for moving it on the track while the band-knife and sewing machine are in operation.
14. The combination in a machine having a pattern-cam control, of a sewing machine equipped with an eye-pointed needle having a two-arm looper, the latter having a point for separating the edges of a slit in goods being sewn; a goods-cutter; a sewing machine provided with the eye-pointed needle; means for moving the sewing machine while stitching; and means for forming a slit in the goods the edges of which are to be stitched.
15. The combination in a machine having a pattern-cam control, of upper and under stitch-forming devices; and a throat-plate; with a thread-breaker, and means for actuating it to break the threads coming from a stitch; a sewing machine comprising said instrumentalities; means for moving the sewing machine while it is stitching; and operative connections between said means and the thread-breaker.
16. The combination in a machine having a pattern-cam control, of a movable sewing machine; a track therefor; means for moving the sewing machine on its track while stitching; a thread-breaking mechanism; means for actuating the thread-breaking mechanism; a pattern cam; and a goods-cutting mechanism.
17. The combination in a machine having a pattern-cam control, of a movable sewing machine; a track therefor; means for moving the sewing machine on its track while it is sewing a predetermined distance; a thread-breaking mechanism; and means for actuating the breaking mechanism when the predetermined length of sewing has been accomplished; and means for actuating the breaking mechanism while the sewing machine is traveling.
18. The combination in a machine having a pattern-cam control, of a movable sewing machine; a track therefor; means for moving the sewing machine on its track while it is sewing a predetermined distance; a thread-breaking mechanism; means for actuating the breaking mechanism when the predetermined length of sewing has been accomplished; means for actuating the breaking mechanism while the sewing machine is traveling; and a goods-cutting mechanism constructed and operating to cut the goods edge which is to be sewn.
19. The combination in a machine having a pattern-cam control, of a movable sewing-machine; a track therefor; a pattern cam; means operatively connecting the sewing machine and the pattern cam for effecting travel of the sewing machine while sewing; a pair of feed rolls parallel with the sewing-machine track; a pair of other feed rolls parallel with the track; the track being in front of both pairs of feed rolls; a removable spreader for tubular goods; a jig-knife; means for operating the jig-knife in a plurality of planes; a crotch-piece end cutting-off mechanism; and a crotch-piece deflector.
20. The combination in a machine having a pattern-cam control, of a distender for tubular goods; a goods-feeding mechanism; a rotary cutter; and means for operating it in contact with an edge of the goods on the spreader; a pair of feed rolls for the goods; stitch-forming instrumentalities; and means for arresting the operation of the stitch-forming instrumentalities during the operation of the rotary cutter.
21. The combination in a machine having a pattern-cam control, of a distender for tubular goods; a goods-feeding mechanism; a motor support; a motor the shaft of which is provided with a cutter; and means for

detachably holding the motor on its support in front of the feed-rolls; a movable implement-carrying mechanism; a pattern cam; and connections between the pattern 5 cam and the implement-carrying mechanism for moving the latter during its operation.

22. The combination in a machine having a pattern-cam control, of a sewing machine; a track therefor; means for moving the 10 sewing machine on its track while it is stitching; a shaft-engaging stop-motion comprising an oil-cushion-forming means; means whereby the oil cushion takes up the coupling shock in stopping the machine; 15 and means for actuating the stop-motion during the travel of the sewing machine; said means for moving the sewing machine on its track comprising a pattern cam and operative connections between the pattern 20 cam and the sewing machine; and mechanism under the control of the pattern cam for operating the means which actuate the stop motion.

23. The combination in a machine having a pattern-cam control, of a sewing machine; a track therefor; means for moving the 25 sewing machine during the stitching operation; a shaft-engaging stop-motion comprising an oil-cushion-forming means; means whereby the oil cushion takes up the coupling shock in stopping the machine; means for automatically supplying oil to create and maintain the cushion; and means for operating the stop-motion while the 30 sewing machine is sewing; said means for moving the sewing machine comprising a pattern cam and operative connections between the pattern cam and the sewing machine; and mechanism controlled by the pattern 35 cam for actuating the means which operate the stop motion.

24. The combination in a machine having a pattern-cam control, of a sewing machine; a track therefor; and means for moving the 40 sewing machine on the track while sewing; the machine having a drive-shaft; a stop-motion for the drive-shaft and carried by the machine; a raisable and lowerable trolley rail; a stop-motion-actuating lever carried by the sewing machine, working on the trolley rail and provided with oil-receiving mechanism; means for automatically lubricating the stop-motion during the travel of the 45 machine; and means for automatically lubricating the actuating lever mechanisms during the travel of the machine.

25. The combination in a machine having a pattern-cam control, with an implement-carrying traveling head, a track therefor, 50 and means for moving the head on the track, the head comprising a shaft for actuating the implements carried by it; of a stop-motion for the shaft and carried by the head; a stop-motion-actuating lever carried

by the head; means for lifting and lowering 55 such actuating lever during the travel of the head; and means for automatically lubricating the stop-motion during the travel of the head, the actuating lever containing mechanisms coöperating with the 60 stop-motion; and means for automatically lubricating such mechanisms during the travel of the machine.

26. The combination in a machine having a pattern-cam control, with an implement-carrying traveling head, a track therefor, 75 and means for moving the head on the track, the head comprising a shaft for actuating the implements carried by it; of a stop-motion for the shaft and carried by the head; a stop-motion-actuating lever comprising an oil-receiver, a therewith-connected chamber, a plunger, a perforated casing therefor, a spring between the plunger and its casing; means for operating said 80 lever for actuation of the stop-motion during the travel of the head; means for automatically lubricating the stop-motion parts 85 during the travel of the head; and means for automatically oiling the actuating lever 90 mechanisms during the travel of the machine.

27. The combination in a machine having a pattern-cam control, of an implement-carrying head; a track therefor; means for 95 moving the head on the track; the head comprising a drive-shaft; a stop-motion for the shaft and inclosing the shaft and having an outwardly-projecting lever; a stop-motion-actuating lever; means for moving the 100 lever to actuate the stop-motion during the travel of the head, said stop-motion-actuating lever being provided with a lever engageable with the lever projecting from the stop-motion; an end of the actuating lever 105 adjacent to the stop-motion being provided with mechanism coöperative with a spring-controlled endwise-movable finger carried by the forward portion of the stop-motion-actuating lever, and the finger coöperating 110 with a member of the stop-motion; means for automatically oiling the stop-motion parts during the travel of the machine; and means for automatically oiling, during the 115 travel of the machine, the said coöperating mechanisms carried by the stop-motion-actuating lever.

28. The combination in a machine having a pattern-cam control, of a rotatable shaft formed with peripheral pockets; a wedge 120 in each pocket, each wedge having a ball-support groove eccentric to the axis of the shaft; a sleeve mounted freely on the shaft, a portion of the sleeve holding the wedges in the pockets and another portion of the 125 sleeve having circumferentially-arranged wall holes inclosing the balls; a ball-retaining ring; a belt-wheel fixedly connected

- with a ball-retaining ring and running freely on said sleeve; a lengthwise-extending exterior annular and eccentric tooth on the sleeve, the sleeve having a T-slot; a key 5 for the shaft of the T-slot; a pin on the sleeve and extending in the direction of the length of the sleeve; a spring having one end attached to the pin and its other end attached to the key; an end bearing to the 10 sleeve; a brake-shoe mounted in a recess of the sleeve; a pressure-plug bearing on the brake-shoe; a lever for lifting the pressure-plug and pivoted on a housing; said housing; a coil spring for the pressure plug; the 15 housing having an oil chamber; a pivoted lever, one end of which projects outwardly from the housing and the other end of which lies between the brake-shoe and the plunger; stop-motion-actuating means; means 20 for actuating the stop-motion-actuating means; a sewing machine of which said shaft constitutes a member; a track for said sewing machine; and means for moving the sewing machine on its track.
- 25 29. The combination in a machine having a pattern-cam control, of a sewing machine; a track therefor; means for moving the sewing-machine on the track; a pattern cam; operative connections between the pattern cam and the sewing machine for moving the latter on its track while sewing; a thread-measuring mechanism comprising a cam-actuator turning with the pattern cam; a 30 thread-breaking mechanism comprising a cam-actuator turning with the pattern cam; a stop-motion for the drive-shaft of the sewing machine; and a stop-motion-actuating mechanism comprising a cam-actuator turning with the pattern cam.
- 35 30. The combination in a machine having a pattern-cam control, of a pattern cam; a sewing machine; a track therefor; operative connections between the pattern cam and the sewing machine for moving the latter on its track while sewing; a thread-measuring mechanism comprising a cam-actuator turning with the pattern cam; a 40 thread-breaking mechanism comprising a cam actuator turning with the pattern cam; a stop-motion for the drive-shaft of the sewing-machine; a stop-motion-actuating mechanism comprising a cam actuator turning with the pattern cam; and a goods-cutting mechanism comprising a cam actuator 45 turning with the pattern cam.
- 45 31. The combination in a machine having a pattern-cam control, of a sewing machine; a track therefor; a pattern cam; operative connections between the pattern cam and the sewing machine for moving the latter on its tracks while sewing; a thread-measuring mechanism; a thread-breaking mechanism; a cutting mechanism; each of said mechanisms comprising actuating means 50 turning with the pattern cam.
- 55 32. The combination in a machine having a pattern-cam control, of a sewing machine; a track therefor; a pattern cam; operative connections between the pattern cam and the sewing machine for moving the latter on its track while sewing; a thread-breaker mechanism comprising a throat plate having a thread clearance rearward of the needle hole; an under thread-breaker slide having an elongated needle-hole; a plate 60 fixed to the throat plate to keep the breaker slide in place, the plate having on its inward side a transverse under-thread clamping rib coöperating with the front end of the breaker slide to clamp the thread; and a goods feeding mechanism.
- 65 33. The combination in a machine having a pattern-cam control, of a sewing machine; a track therefor; a pattern cam; operative connections between the pattern cam and the sewing machine for moving the latter on its track while sewing; a thread-breaker mechanism comprising a throat plate having a thread clearance rearward of the needle hole; an under thread-breaker slide having an elongated needle-hole; a plate fixed to the throat plate to keep the breaker slide in place, the plate having on its inward side a transverse under-thread clamping rib co-operating with the front end of the breaker slide to clamp the thread; a goods feeding mechanism; and upper and under stitch-forming devices; all arranged to secure movement of the work and by such movement to drag the looper thread against the breaker plate and also to draw the needle thread rearward and around the under stitch-forming device.
- 70 34. The combination in a machine having a pattern-cam control, of a sewing machine; a track therefor; a pattern cam; operative connections between the cam and the sewing machine for moving the latter on its track while sewing; a thread-measuring mechanism carried by the sewing machine and comprising a trip-lever and a thread-measuring lever; the trip-lever being constructed to be held in an inoperative position by the thread during stitching, and to move on accidental breakage of the thread; stop devices to hold the trip-lever while the thread is being measured off or broken mechanically at the end of a stitching operation; and the thread-measuring lever being constructed to measure off a supply of thread to start the next stitching operation.
- 75 35. The combination in a machine having a pattern-cam control, of a sewing machine; a track therefor; a pattern cam; operative connections between the cam and the sewing machine for moving the latter on its track while sewing; a thread-measuring mechanism carried by the sewing machine and comprising a trip-lever and a thread-measuring lever; the trip-lever being con-

structed to be held in an inoperative position by the thread during stitching, and to move on accidental breakage of the thread; stop devices to hold the trip-lever while the 5 thread is being measured off or broken mechanically at the end of a stitching operation; and the thread-measuring lever being constructed to measure off a supply of thread to start the next stitching operation; and a 10 thread-breaking mechanism.

36. The combination in a machine having a pattern-cam control, of a sewing machine; a track therefor; means for moving the sewing machine on its track while sewing; a 15 four-motion jig-knife; means for operating the jig-knife; feed rolls for the goods; crotch-piece feed rolls; a crotch-piece deflector; and a crotch-piece cutting-off mechanism; said means for moving the sewing 20 machine comprising a pattern cam and operative connections between the sewing machine and the pattern cam; and the means for operating the jig knife and the crotch-piece-cutting-off mechanism being operatively connected with the pattern cam.

37. The combination in a machine having a pattern-cam control, of a sewing machine; a track therefor; means for moving the sewing machine on its track while sewing; an 30 under band-knife wheel; means for rotating it while the sewing machine travels; a four-motion jig-knife carried by the sewing machine; a mechanism comprising a crank from which the jig-knife is operated; means 35 operatively connecting the jig-knife with the crank and fixed on the crank; a driving-roll engaging and rotated by the band-knife wheel; said means for moving the sewing machine comprising a pattern cam and operative 40 connections between it and the sewing machine; and the jig-knife being operatively connected with the pattern cam.

38. The combination in a machine having a pattern-cam control, of a sewing machine; a track therefor; means for moving the sewing machine on its track while sewing; a four-motion jig-knife carried by the sewing machine and operating adjacent the sewing devices; means for reciprocating the 50 knife; and means for vibrating the jig-knife; the said means for reciprocating the jig-knife and for vibrating the jig-knife giving it a four-motion movement; said means for moving the sewing machine comprising a pattern cam and operative connections between the pattern cam and the sewing machine; and operative connections between the jig-knife-actuating mechanism and the pattern cam.

39. The combination in a machine having a pattern-cam control, of a sewing machine; a track therefor; means for moving the sewing machine on its track; a jig-knife carried by the sewing machine and operative adjacent the stitch-forming devices; and means

for operating the jig-knife, such means comprising a hollow crank-shaft having an inlet port and an oil-outlet duct; said means for moving the sewing machine on its track comprising a pattern cam and operative 70 connections between it and the sewing machine; and the means for operating the jig-knife being operatively connected with the pattern cam.

40. The combination in a machine having a pattern-cam control, of a sewing machine; a track therefor; means for moving the sewing machine on its track; a jig-knife operative adjacent the stitch-forming devices; jig-knife-actuating mechanism comprising a 80 cam-control turning with a pattern cam from which the sewing machine is moved on its track; said pattern cam; a goods-feeding mechanism; and a transverse cutting mechanism operating in the path of the feed of 85 the goods; and a mechanism for actuating it alternately with the actuation of the jig-knife.

41. The combination in a machine having a pattern-cam control, of a sewing machine; a track therefor; means for moving the sewing machine on its track; and a pair of feed rolls parallel with the track; the sewing machine comprising a work-engaging pivoted foot having lifting and pressing movements 95 while engaging the goods being fed and due to variations in the thickness of such goods.

42. The combination in a machine having a pattern-cam control, of a sewing machine; a track therefor; means for moving the sewing machine on its track, such means comprising a pattern cam, a stop-motion carried by the sewing machine for its drive-shaft, a raisable and lowerable trolley rail, a stop-motion-actuating device carried by the sewing machine and working on the trolley rail, means for raising the trolley rail positively; a thread-measuring mechanism comprising an actuator turning with the pattern cam; a thread-breaking mechanism comprising an 110 actuator turning with the pattern cam; a work-engaging foot automatically liftable by variations in thickness of goods being fed, a pair of feed rolls removed from the sewing machine and parallel with the track; a 115 jig-knife carried by the sewing machine and operative adjacent the stitch-forming instrumentalities; a crotch-piece cut-off mechanism; and crotch-piece deflecting mechanism; the jig-knife, cut-off mechanism, and crotch-piece deflector being automatically actuated by means turning with the pattern cam.

43. The combination in a machine having a pattern-cam control of a sewing machine; a track therefor; means for moving the sewing machine on its track, such means comprising a pattern cam, a stop-motion carried by the sewing machine for its drive-shaft, a raisable and lowerable trolley rail, a stop- 120

- motion-actuating device carried by the sewing machine and working on the trolley rail; means for raising the trolley rail; a thread-measuring mechanism comprising an actuator turning with the pattern cam; a thread-breaking mechanism comprising an actuator turning with the pattern cam; a work-engaging foot automatically liftable by variations in thickness of goods being fed; a 5 pair of feed rolls removed from the sewing machine and parallel with the track; a jig-knife carried by the sewing machine and operative adjacent the stitch-forming instrumentalities; a crotch-piece cut-off mechanism; and crotch-piece deflecting mechanism; the jig-knife, cut-off mechanism, and crotch-piece deflector being automatically actuated by means turning with the pattern cam.
- 10 44. The combination in a machine having a pattern-cam control, of a sewing machine; a track therefor; means for moving the sewing machine on its track, such means comprising a pattern cam, a stop-motion carried by the sewing machine for its drive-shaft, a raisable and lowerable trolley rail, a stop-motion-actuating device carried by the sewing machine and working on the trolley rail, means for raising the trolley rail; a thread-measuring mechanism comprising an actuator turning with the pattern cam; a thread-breaking mechanism comprising an actuator turning with the pattern cam; a work-engaging foot automatically 15 liftable by variations in thickness of goods being fed; a pair of feed rolls removed from the sewing machine and parallel with the track; a jig-knife carried by the sewing machine and operative adjacent the stitch-forming instrumentalities; a crotch-piece cut-off mechanism; and crotch-piece deflecting mechanism; the jig-knife, cut-off mechanism, and crotch-piece deflector being automatically actuated by means turning with the pattern cam; said mechanisms being each operatively connected with trolley-rail-lifting mechanism; the stop-motion-actuating device working on the trolley rail.
- 20 45. The combination in a machine having a pattern-cam control, of a sewing machine having a throat plate recessed at its front edge to form an inside projection, said projection being bent down; a track for the sewing machine; a pattern cam; operative connections between the pattern cam and the sewing machine for moving the latter on its track; a pair of feed rolls parallel with the track and on the sewing machine; a work-foot automatically raisable by variations in thickness of the goods being fed.
- 25 46. The combination in a machine having a pattern-cam control, of a movable sewing-machine; a track therefor; a pattern cam; operative connections between the pattern cam and the sewing machine for moving
- it on its track while sewing; a jig-knife mechanism; a stop-motion mechanism for the sewing machine; goods-feeding mechanism; a crotch-piece cutting-off mechanism; arm-hole cutting mechanism; a goods 70 spreader; and means for positioning the goods on the spreader while the goods there-around are being fed by the goods-feeding mechanism.
- 30 47. The combination in a machine having a pattern-cam control, of a sewing machine; a track therefor; a pattern cam; operative connections between said cam and the sewing machine for moving the latter while sewing; a trolley-rail mechanism; a stop-motion for the drive-shaft of the sewing machine and carried by the machine; a stop-motion-actuating mechanism carried by the machine and co-operatively connected with the trolley mechanism; a goods-feeding mechanism; a 75 jig-knife; jig-knife-operating mechanism; a transverse crotch-piece cutter; such cutter-actuating mechanism; an arm-hole cutter and arm-hole-cutter actuating means; the jig-knife-operating means, the trolley- 80 mechanism-operating means, the crotch-piece-cutter-operating means, and arm-hole-cutter-operating means each comprising a cam on the peripheral surface of the pattern cam.
- 35 48. The combination in a machine having a pattern-cam control, of a sewing machine; a track therefor; means for moving the sewing machine on its track; the sewing machine comprising a needle-thread-measuring 85 mechanism comprising a top lever having a thread eye at its free end, a measuring lever having a thread eye in its free end, a needle-thread tension, said thread eyes being intermediate the needle and the tension, a thread- 90 nipper intermediate the needle and the thread eyes, a needle supply, a needle-thread tension intermediate such supply and said other tension, actuating mechanism for the thread-measuring lever, such mechanism comprising a slide, and a raisable and lowerable track for the slide; a controller cam, and operative connections between the cam and said raisable and lowerable track mechanism for actuating the trip-lever, such 95 mechanism comprising a latch-device, connections between the latch-device and the slide, stop-devices for the trip-lever, a switch-lever co-operating with the mechanism for actuating the trip-lever; the sewing machine carrying the trip-lever; electrical leads and connections along the sewing-machine track; an electrode carried by the switch-lever and adapted to make and break contact with the leads; and a goods- 100 feeding mechanism; the thread-measuring mechanism being constructed to nip the thread near the needle for the retention of thread in the needle eye during a forward movement of the goods and while the needle 105
- 40 49. The combination in a machine having a pattern-cam control, of a sewing machine having a throat plate recessed at its front edge to form an inside projection, said projection being bent down; a track for the sewing machine; a pattern cam; operative connections between the pattern cam and the sewing machine for moving the latter on its track; a pair of feed rolls parallel with the track and on the sewing machine; a work-foot automatically raisable by variations in thickness of the goods being fed.
- 45 50 51 52 53 54 55 56 57 58 59 60 61 62 63 64 65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130

is up, to measure off thread for commencing the next stitching movement, to keep the lever inactive during the thread-measuring operation, to hold the switch-lever out of electrical contact during the thread-measuring operation and when the thread is broken mechanically, and to permit the switch-lever to move into electrical contact when a thread breaks accidentally during a stitching operation, the main-shaft and starting-post clutch mechanism, the starting-post, a raisable and lowerable trolley track, operative connections between the means for moving the sewing machine and the trolley rails, a stop-motion for the sewing-machine drive-shaft, and a stop-motion-actuating device carried by the sewing machine and working on the trolley rail.

49. The combination in a machine having a pattern-cam control, of a sewing machine; a track therefor; means for moving the sewing machine on its track; the sewing machine comprising a needle-thread-measuring mechanism comprising a top lever having a thread eye at its free end, a measuring lever having a thread eye in its free end, a needle-thread tension, said thread eyes being intermediate the needle and the tension, a thread-nipper intermediate the needle and the thread eyes; a needle supply, a needle-thread tension intermediate such supply and said other tension, actuating mechanism for the thread-measuring lever, such mechanism comprising a slide, and a raisable and lowerable track for the slide; a controller cam and operative connections between the cam and said raisable and lowerable track mechanism for actuating the trip-lever, such mechanism comprising a latch-device, connections between the latch-device and the slide, stop-devices for the trip-lever, a switch-lever coöperating with the mechanism for actuating the trip-lever; the sewing machine carrying the trip-lever; electrical leads and connections along the sewing-machine track; an electrode carried by the switch-lever and adapted to make and break contact with the leads; and a goods-feeding mechanism; the thread-measuring mechanism being constructed to nip the thread near the needle for the retention of thread in the needle eye during a forward movement of the goods and while the needle is up, to measure off thread for commencing the next stitching movement, to keep the lever inactive during the thread-measuring operation, to hold the switch-lever out of electrical contact during the thread-measuring operation and when the thread is broken mechanically, and to permit the switch-lever to move into electrical contact when a thread breaks accidentally during a stitching operation, the main-shaft and starting-post clutch mechanism, the starting-post, a raisable and lower-

able trolley track, operative connections between the means for moving the sewing machine and the trolley-rails; a stop-motion for the sewing-machine drive-shaft, and a stop-motion-actuating device carried by the sewing machine and working on the trolley rail; and the thread-breaking mechanism operatively connected with said slide.

50. The combination in a machine having a pattern-cam control, of a sewing machine; a track therefor; means for moving the sewing machine on its track while it is sewing; feed-rolls spaced apart from the sewing machine and parallel with the track; the sewing machine having a goods work-foot provided with elongated needle holes, and rearwardly of said needle holes an upstanding transverse rib, said work-foot being constructed and operating to glide over the goods and to yield to variations of the thickness of the goods in gliding thereover during the travel of the machine.

51. The combination in a machine having a pattern-cam control, of a sewing machine; a track therefor; means for moving the sewing machine on its track while it is sewing; feed-rolls spaced apart from the sewing machine and parallel with the track; the sewing machine having a goods work-foot provided with elongated needle holes, and rearwardly of said needle holes an upstanding transverse rib; and means for moving the sewing machine on its track while it is out of stitching action; said work-foot being constructed and operating to glide over the goods and to yield to variations of the thickness of the goods in gliding thereover during the travel of the machine.

52. The combination in a machine having a pattern-cam control, of a sewing machine; a track therefor; and means for moving it on its track; the sewing machine being provided with a dependent goods-engaging-foot supporting-arm, and the arm having a thereon-pivoted foot; a spring between the support and the pivoted foot; and means for adjusting the position of the foot; such foot being automatically operable to yield to variations of the thickness of the goods and to glide thereover during the travel of the machine.

53. The combination in a machine having a pattern-cam control, of a sewing machine; a track therefor; means for moving the machine on the track while it is sewing; and goods-feeding rolls parallel with the track; a sewing machine having a needle holder carrying a thread-nipper and provided with thread eyes; and a work-foot constructed and operating to glide over the goods and to yield to variations of the thickness of the goods while gliding thereover during the travel of the machine.

54. The combination in a machine having a pattern-cam control, of a sewing machine;

5 a track therefor; and means for moving the sewing machine on the track while it is sewing; the top shaft of the sewing machine being provided with a pair of cranks; and the under arm of the sewing machine carrying a lengthwise-movable rockable hollow looper-shaft provided with a crank and containing a forward fixed abutment for a spring; the spring; a sliding abutment for the rearward end of the spring; and rearwardly of and spaced apart from the sliding abutment a fixed abutment; a bell-crank lever pivoted on the machine frame and having one arm between said rearward fixed abutment and the sliding abutment; a link connecting one of the top-shaft cranks with a crank on the other end of said bell-crank; and a link between the other crank of the top-shaft and the crank on the rear end of 10 the looper shaft.

15 55. The combination in a machine having a pattern-cam control, of a sewing machine; a track therefor; a pattern cam and connections for moving the sewing machine on its track; the main shaft of the sewing machine-carrying machine; a starting-post; a clutch mechanism between the starting-post and the main shaft; a jointed raisable and lowerable trolley-rail connected with the 20 starting post; a stop motion for the sewing machine; a stop-motion-actuating lever carried by the sewing machine and working on the trolley rail; the trolley rail having for actuation of said stop-motion a pair of dependent pivoted links spaced laterally apart; a bell-crank lever pivoted to the sewing machine, one for each link, the lower end of which is pivoted to an arm of the bell-crank; a link pivotally connected to and 25 uniting the other arms of the bell crank; a link pivotally connected to the lower arm of the outward bell-crank, such link being pivoted at its inward end to the upstanding arm of a bell-crank pivoted to the machine frame, and the lower arm of the last-mentioned bell-crank being provided with a roller to engage a cam turning with the pattern cam.

30 56. The combination in a machine having a pattern-cam control, of a sewing machine; a track therefor; a pattern cam and connections for moving the sewing machine on its track; the main shaft of the machine supporting the traveling sewing machine; a starting-post; a clutch mechanism between the starting-post and the main shaft; a jointed raisable and lowerable trolley-rail connected with the starting post; a stop motion for the sewing machine; a stop-motion- 35 actuating lever carried by the sewing machine and working on the trolley rail; the trolley rail having for actuation of said stop-motion a pair of dependent pivoted links spaced laterally apart; a bell-crank lever

40 pivoted to the sewing machine, one for each link, the lower end of which is pivoted to an arm of the bell-crank; a link pivotally connected to and uniting the other arms of the bell crank; a link pivotally connected to the lower arm of the outward bell-crank, such link being pivoted at its inward end to the upstanding arm of a bell-crank pivoted to the machine frame, and the lower arm of the last-mentioned bell-crank being provided with a roller to engage a cam turning with the pattern cam; the end of the link pivoted to the dependent end of said outward cam being lengthwise slotted for reception of the pivot pin at the outward end thereof; an outwardly-extending link pivoted to said pivot pin and having its outward end pivoted to the dependent arm of the bell-crank, the other end of which is pivoted to a slide, this bell-crank being pivoted to the machine frame; a track for said slide; a bell-crank pivoted to the machine frame and having one arm pivoted to said track for the slide and its other arm pivoted to a link the outward end of which is pivoted to the dependent arm of the bell-crank pivoted to the slide; a thread-measuring mechanism operatively connected with the track for the slide; and the thread-breaking mechanism operatively connected with the slide.

45 57. The combination in a machine having a pattern-cam control, of a sewing machine; a track therefor; means for moving the sewing machine on the track; and a pair of feed-rolls spaced apart from the sewing machine and parallel with the sewing-machine track; the top-shaft of the sewing machine being provided with a crank arm, a needle-link pivoted to the crank arm, a needle-holder pivoted to the link, a dependent needle-holder guide, an automatically raisable goods foot, a link pivoted to the crank arm, a bell-crank pivoted to the machine head and having one arm pivoted to the last-mentioned link, a pitman pivoted to the bell-crank and adjustably connected with a looper finger, the looper finger being pivoted to the machine head, a link pivoted at one end to the machine and at its other end to the looper finger intermediate the ends thereof, the looper finger being provided with a pair of looper jaws whereof the upper jaw is formed with a hook and the under jaw with an eye; and a work-foot constructed and operating to glide over the goods and to yield to variations of the thickness of the goods while gliding thereover during the travel of the machine.

52 58. The combination in a machine having a pattern-cam control, of a sewing machine; a track therefor; a pattern cam operatively connected with the sewing machine for moving it on its track while sewing; a jig-knife

- operative adjacent the needle; means for operating the jig-knife; a crotch-piece-deflecting mechanism; means for operating such mechanism; and a crotch-piece cut-off mechanism comprising a pair of cutting edges spaced apart and extending transversely of the feed path of the goods, and a reciprocating cutter mounted between said pair of cutting edges; and means for reciprocating said cutter.
59. The combination in a machine having a pattern-cam control, of a sewing machine, a track therefor, a pattern cam operatively connected with the sewing machine for moving it on its track while sewing, feed rolls parallel with the track, a tubular goods-spreader, and means for oppositely slitting the opposed top and bottom walls of the goods.
60. The combination in a machine having a pattern-cam control, of a sewing machine, a track therefor, a pattern cam operatively connected with the sewing machine for moving it on its track while sewing, feed rolls parallel with the track, a tubular goods-spreader, means for oppositely slitting in alignment the opposed flattened walls of the goods, and means for varying the length of the slitting movement through one wall 30 of the goods relatively to the slit in the opposed wall thereof.
61. The combination in a machine having a pattern-cam control, of a sewing machine, a track therefor, a pattern cam operatively connected with the sewing machine for moving it on its track while sewing, a pair of feed rolls, a tubular goods-spreader, and means for lengthwise slitting an edge of the goods flattened on the spreader during the feeding movement of the feed-rolls, and means for driving the feed-rolls.
62. The combination in a machine having a pattern-cam control, of a sewing machine, a track therefor, a pattern cam operatively connected with the sewing machine for moving it on its track while sewing, an auxiliary cutter-actuating cam, a rock-shaft carrying a roller working on the actuating cam, a spring to hold the roller in proper contact with the cam, a track pivotally connected with the rock-shaft, a cutter, means operatively connecting the cutter with the track, and means carrying the cutter and working on the track, the cutter being operable while the cutter-carrying means is traveling on the track.
63. The combination in a machine having a pattern-cam control, of a sewing machine, a track therefor, a pattern cam operatively connected with the sewing machine for moving it on its track while sewing, a trolley rail, a stop-motion for the drive-shaft of the sewing machine carried by the stop-motion and having an actuating lever work-
- ing on the trolley rail, and for lifting the trolley rail automatically a link mechanism comprising a slotted connection, a spring and a stop-pin.
64. The combination in a machine having a pattern-cam control, of a sewing machine, a track therefor, a pattern cam, and connections for moving the sewing machine on its track, goods-separating means carried by the sewing machine adjacent the stitch-forming instrumentalities, and means for holding the edges of an upper and under wall of the goods as they are separated in position to be sewn together as they are cut; and means to spread the cut edges laterally apart.
65. The combination in a machine having a pattern-cam control, with an implement-carrying traveling head, a track therefor, means comprising a cam and connections therewith for shifting the head along the track, said implements being located at the free end of the head and some constructed to spread the cut edges of superimposed strips of goods laterally apart, and some to join the upper and under wall of the goods as they are separated, the joining means comprising a covering formed over the edges of the goods; and stitch-forming instrumentalities.
66. The combination in a machine having a pattern-cam control, with an implement-carrying traveling-head, an upper and lower track therefor, stitch-forming devices, and goods-separating devices both acting on the goods intermediate the outside edges thereof, feed rollers adjacent the tracks, a stop-motion to arrest the stitching, a mechanism to render the separating implements effective or non-effective, and means to shift the implement-carrying head on the tracks without effecting the feed of the goods.
67. The combination in a machine having a pattern-cam control, of a sewing machine, a track therefor, a pattern cam operatively connected with the sewing machine, another sewing machine mounted on said track and operatively connected with said cam, a goods spreader, means for oppositely forming arm-hole slits in the edges of goods distended on the spreader, means for cutting the crotch-piece from between the edges of distended goods, crotch-piece-removing means, and means for slitting the flat walls of the goods lengthwise.
68. The combination in a machine having a pattern-cam control, of a tubular-goods spreader; a goods-feeding mechanism; means for slitting openings in opposite edges of the spread goods as the goods are fed; means for simultaneously cutting the goods lengthwise in a plurality of lines between the edges of the goods as the goods are fed; means for severing the ends of por-

- tions of the goods partially separated from the main portion thereof while the goods are being fed; and mechanism for sewing together the cut edges of the main portion of the goods during the feeding movement thereof.
69. The combination in a machine having a pattern-cam control, of a tubular-goods spreader; a goods-feeding mechanism; means for slitting openings in opposite edges of the spread goods as the goods are fed; means for simultaneously cutting the goods lengthwise in a plurality of lines between the edges of the goods as the goods are fed; means for severing the ends of portions of the goods partially separated from the main portion thereof while the goods are being fed; and mechanism for sewing together the cut edges of the main portion of the goods during the feeding movement thereof; the means for cutting the goods lengthwise comprising cutters adapted to slit a wall of the spread goods lengthwise in divergent lines.
70. The combination in a machine having a pattern-cam control, of a tubular-goods spreader; and goods-feeding mechanism; with means for cutting the spread goods lengthwise in a plurality of cuts spaced apart and angularly disposed one in relation to the other and formed between the edges of the goods, thereby forming pieces for removal between leg-forming portions of the goods; means for separating such portions from the rest of the goods; and seaming mechanisms constructed simultaneously to seam up the inside cut edges of the leg-forming portions.
71. The combination in a machine having a pattern-cam control of a tubular-goods spreader; and goods-feeding mechanism; with means for cutting the spread goods lengthwise in a plurality of cuts spaced apart and angularly disposed one in relation to the other and formed between the edges of the goods, thereby forming pieces for removal between leg-forming portions of the goods; means for separating such portions from the rest of the goods; seaming mechanisms constructed simultaneously to seam up the inside cut edges of the leg-forming portions; and means for slitting the opposed walls of the spread goods lengthwise in slits which intersect the opening formed by removal of the goods from between the leg-forming portions.
72. The combination in a machine having a pattern-cam control, of a tubular-goods spreader; and goods-feeding mechanism; with means for cutting the spread goods lengthwise in a plurality of cuts spaced apart and formed between the edges of the goods, thereby forming pieces for removal between leg-forming portions of the goods; means for separating such portions from the rest of the goods; seaming mechanisms constructed simultaneously to seam up the inside cut edges of the leg-forming portions; and means for slitting the opposed walls of the spread goods lengthwise in slits which intersect the opening formed by removal of the goods from between the leg-forming portions; and means for simultaneously cutting the goods lengthwise in a plurality of lines between the edges of the goods as the goods are fed; means for severing the ends of portions of the goods partially separated from the main portion thereof while the goods are being fed; and mechanism for sewing together the cut edges of the main portion of the goods during the feeding movement thereof.
73. The combination of a pattern cam; an implement-carrying head; operative connections between the pattern cam and the implement-carrying head for moving the latter during its operation; a track for the implement-carrying head; a trolley rail; positive means operatively connecting the trolley rail and the pattern cam for raising the trolley rail positively; and a stop motion for the implement-carrying head attached thereto and operable by the trolley rail; said positive means being composed of a series of levers, bars and links, a link being connected with the trolley rail, and one of the levers being in operative mechanical relation to the pattern cam.
74. The combination of a trolley rail for a traveling implement-carrying head, with a cam and intermediate mechanism constructed and operating to lift and lower the trolley rail and comprising a link connected to the trolley rail, and a cam roll coöperating with the cam, and a series of positively-acting levers and bars which communicate the cam-roll movements to the link.
75. The combination of a trolley rail for a traveling implement-carrying head, with a cam and intermediate mechanism constructed and operating to lift and lower the trolley rail and comprising a link connected to the trolley rail, and a cam roll coöperating with the cam, and a series of positively-acting levers and bars which communicate the cam-roll movements to the link; a thread-breaker mechanism comprising a raisable and lowerable track; and operable connections between it and said levers and bars.
76. The combination of a trolley rail for a traveling implement-carrying head, with a cam and intermediate mechanism constructed and operating to lift and lower the trolley rail and comprising a link connected to the trolley rail, and a cam roll coöperating with the cam, and a series of positively-acting levers and bars which communicate the cam-roll movements to the link; a thread-breaker mechanism comprising a raisable and lowerable track; and operable connections between it and said levers and bars; and thread-controlling devices and operable connections between them and said track.

77. The combination of a traveling implement-carrying head, a track therefor, a pattern cam, connections operatively connecting the pattern cam with the traveling implement-carrying head, a cutter-actuating cam, cutting mechanism, operative connections between the cutter-actuating cam and the cutter, a stop-motion for the implement-carrying head, a raisable and lowerable trolley rail for said stop-motion, positively acting mechanism operatively connecting the trolley rail with a trolley-rail raising and lowering cam, such cam, and a cutter-actuating cam operatively connected with the cutter-actuating mechanism.

78. The combination of a bodily-movable implement-carrying head; a drive-shaft in said head for operation of the implement or implements carried thereby; a stop-motion for said drive-shaft; a lubricant-container carried by the head; an oil pump in operative connection with the container and having an actuating member; the stop motion being provided with a lubricant-receiving duct; a conduit leading from the pump and discharging lubricant to said duct; a power device on said shaft; a motor carried by said head and having on its shaft a power-transmitting device; and a belt from said transmitting device to said power device and running in driving connection with the pump-actuating member; a track for said head; means for reciprocating the head on the track; and mechanism for actuating said stop-motion.

79. In the structure of claim 78, the pump being located within the lubricant container and having its actuating member projecting therefrom into the path of the belt.

80. The combination of a master cam with a jig-knife and intermediate mechanical connections comprising means for giving the jig-knife lateral and also endwise movements, said jig-knife being positioned to cut openings in the goods while passing through the machine, a goods-feeding mechanism, a bodily-movable implement-carrying head, and means connecting such head with the master cam for giving bodily movements to the head.

81. In the structure of claim 80, the jig-knife point being curved and sharpened on its concave edge.

82. In the structure of claim 80, a coöperating knife or ledger-blade for the jig-knife.

83. In the structure of claim 80, a slotted work-plate, and at such slot a stationary ledger blade with which the jig-knife co-operates.

84. In the structure of claim 80, a slotted work-plate; a ledger blade operatively fixed at such slot for coöperation with the jig-knife; and transverse length-cut-off mechanism.

85. The combination of a pair of feed rolls with a pair of arm-hole cutters each being attached to the shaft of an electric motor, and means for moving such motors into and out of cutting position, a pair of 70 bodily-movable sewing-machines, and a master cam operatively connected with each of said sewing machines.

86. The combination of a pair of bodily-movable sewing-machine heads; a master 75 cam operatively connected with each head; on each head a rotary slitter carried by the shaft of a motor fixed to the head; a pair of feed rolls; a transverse length-cut-off mechanism; a spreader for flattened tubular 80 goods located to deliver a flattened tube to the feed rolls; a slotted work-plate; a ledger blade at said slot; a supplementary cutter blade coöperating with said ledger blade; and mechanism operatively connected with 85 the master cam for operating the supplementary cutter blade.

87. The combination of a stationary track for a movable sewing-machine head; said head; a master cam; connections between the cam and the head for moving the latter on its track; a thread-breaking mechanism; and connections between the cam and the thread-breaking mechanism for actuating the latter; and a goods-feeding mechanism; 95 the sewing-machine head comprising stitch-forming devices.

88. In the structure of claim 87, a thread-measuring mechanism, and connections between it and the cam for actuating the measuring mechanism.

89. The combination of a stationary track for a pair of movable sewing-machine heads each equipped with stitch-forming devices; a goods-feeding mechanism comprising a 105 pair of feed rolls parallel to said track; a master cam operatively connected with each head to reciprocate each on the track while stitching traveling goods fed to them by the feed rolls; each head having adjacent the stitch-forming devices a thread-measuring and breaking mechanism comprising a breaker slide operatively connected with the master cam.

90. The combination of a main shaft; a 115 master cam; connections between the shaft and cam for rotating the cam; a starting member comprising a clutch member; a co-120 operating clutch member; a transverse stationary trolley rail operatively connected to one of the clutch members; a transverse stationary track; an implement-carrying head provided with a driving shaft and movably mounted on the track and operatively connected with the master cam, said rail being 125 endwise-movable manually for connecting and disconnecting the clutch members; a stop-motion actuating lever; and a stop-motion mechanism operatively located between said lever and the driving shaft of said head, 130

said stop-motion mechanism comprising automatic means for starting the shaft to which the stop-motion mechanism is connected.

5 91. In the structure of claim 90, the implement-carrying head being provided with stitch-forming devices.

92. In the structure of claim 90, the implement-carrying head being provided with 10 a goods-cutting mechanism.

93. In the structure of claim 90, the implement-carrying head being provided with stitching devices, a thread measuring and breaking mechanism, and a goods-cutting 15 mechanism.

94. In the structure of claim 90, a goods-feeding mechanism, the implement-carrying head being provided with stitch-forming devices, a thread measuring and breaking 20 mechanism, and a rotary cutter.

95. The combination of a goods-feeding mechanism; a stationary track transverse the goods-feed path; a pair of implement-carrying heads slidably mounted on the track; 25 each of such heads carrying a cutter; mecha-

nism for moving each head on the track; and mechanism for the actuation of each cutter; such cutter-actuating mechanism comprising means for causing each cutter during a certain cutting interval to project through a single wall of the goods; thereafter during another cutting interval to become spaced apart from one another; and thereafter to cause each cutter further to diverge from the other and then to cut through both walls of the goods; and a transverse cutter; and means for actuating the latter cutter at a predetermined time; and means for passing the goods in their feed through the machine in opposed wall form; each implement-carrying head being also provided with stitch-forming devices.

In testimony whereof I have hereunto set my hand in the presence of two subscribing witnesses, this 14th day of October, 1914.

JOHN PETER WEIS.
